[57] **ABSTRACT**

A method of and apparatus for fluidically controlling

the sensing, staking and dynamic acoustic resistance adjusting of porous, sintered metal disc-type resistors mechanically fed to and seated within pre-formed apertures in the armature-supporting frame of carbon type telephone transmitter or central armature type receiver units. At a "sensing" station, air flow is established through each acoustic resistor previously positioned within a pre-formed aperture of the frame, and the total resultant back pressure is measured, with the magnitude thereof being used as a control parameter in a fluidic circuit to determine the presence or absence, as well as acceptable or unacceptable position, of one or more resistors which should have previously been seated in the frame. At the "staking" station, the magnitude of a similarly established back pressure is utilized as a control parameter in the fluidic circuit to determine the particular degree of force which should be applied to each resistor by the staking punches during each staking operation. This permits the air flow resistance exhibited by the resistors staked in each frame to be dynamically adjusted within very close limits, regardless of any physical variations that may exist between such resistors as manufactured. Memory circuitry within the fluidic circuit stores information received from both the sensing and staking stations and provides delayed output control signals for selectively operating frame ejection apparatus employed at Accept or Reject stations associated with, but removed from, the sensing and staking stations, respectively.

**APPARATUS FOR FLUIDICALLY CONTROLLING
THE ASSEMBLY AND DYNAMIC RESISTANCE
ADJUSTMENT OF ACOUSTIC RESISTORS**

BACKGROUND OF THE INVENTION

1. Field of the Invention

This invention relates to the manufacture of electrical transducers and, more particularly, to carbon type transmitter and/or central armature type receiver units which are employed in telephones. These units utilize disc-shaped acoustic resistors, generally formed of sintered metallic material of controlled porosity, staked within preformed apertures of a frame member thereof. Such air-flow resistors act as damping devices to limit the degree of physical displacement of the transmitter or receiver diaphragm during normal operation.

It should be understood that the words "acoustic resistor," "acoustic disc" or "air-flow resistor" as used hereinafter are intended to encompass air-flow membranes in general, be they of sintered metallic material or of metallic or non-metallic materials in other forms, and with it being further understood that such membranes may be formed into many shapes other than discs, and used in other applications and for other purposes than those disclosed herein.

2. Description of the Prior Art

In assembling disc-type, sintered metal acoustic resistors within pre-formed apertures in the frame of telephone transmitter or receiver units, a staking operation is required. As such resistors are generally manufactured with a resistance-dependent degree of porosity which is intended to be uniform, any pressure exerted on the resistors which would alter their porosity during the staking operation will quite naturally alter their as-received value of resistance.

Accordingly, in an attempt to achieve consistent staked acoustic resistance values heretofore, great care had been taken in the design of the staking tools and holding fixtures. Unfortunately, however, the resultant acoustic resistance of such resistors, as measured after assembly, was found to vary quite widely on either side of an acceptable range therefor. Investigation revealed that in many cases this resulted from variations in how the resistors were initially seated in the pre-formed undercut apertures of the frame. Improper seating, of course, could alter the spacing between a given resistor and a staking punch and this, in turn, could adversely lead to variations in the amount of metal moved by the punch during a staking operation. In addition, it was found that variations in the final value of acoustic resistance exhibited by the resistors was also due to variations in the size and/or porosity (or alternatively, density) of the sintered disc-type resistors as manufactured.

Unfortunately, the aforementioned variable factors negated any possibility of staking disc-type acoustic resistors with a nominal staking punch force and/or driving stroke, whereby all of the resistors would consistently exhibit a nominal value of acoustic resistance, or fall within an acceptable range of resistances, on a large volume production basis. Moreover, those staked resistors which were subsequently found to be defective necessitated that not only they be scrapped, but also the associated frame in which they were staked.

Such total scrapping was necessary, heretofore, because the actual measurement of acoustic resistance could only be determined following the staking opera-

tion. As such, both the staking and testing operations heretofore were essentially "static" operations. More specifically, with respect to the staking operation, a predetermined nominal staking force and driving stroke were usually employed. As for measuring the acoustic resistance, this was similarly a static test in the sense that it simply involved measuring the "as staked" value of acoustic resistance, with there being no practical way to alter it. Moreover, the problems encountered heretofore in obtaining acceptable, finally staked acoustic resistors were further compounded by the air-to-electric and electric-to-air interface devices required in the measuring apparatus.

More specifically, a diaphragm-actuated pressure switch was utilized to indicate the value of acoustic resistance exhibited by each resistor, or more generally of several resistors in combination in a given frame, with the actual deflection of the diaphragm being utilized to operate electrical contacts of the pressure switch at some predetermined chosen point of diaphragm deflection. Limited diaphragm and switch contact life, unreliable repeatability of the deflection distance vs. pressure characteristics over extended periods and high hysteresis all contributed to the undesirability of using such test apparatus in a high production application. In addition, since air was the medium being used in the actual test, and since air was the medium being used in the power portion of the testing operation, it intuitively seemed to be undesirable to test in air, perform the logic electrically, and then provide the power with air. This reasoning has proved to be correct, at least when applied to the practical application disclosed herein.

SUMMARY OF THE INVENTION

An object of the present invention is to provide a new method of and apparatus for fluidically controlling the assembly of an air flow membrane within an aperture of a supporting structure, and to dynamically adjust the air flow resistance exhibited by the membrane during assembly.

It is another object of this invention to provide a new method of and apparatus for fluidically controlling the staking and acoustic resistance adjusting of porous, disc-type acoustic resistors within pre-formed apertures in the frames of carbon type telephone transmitter and central armature type receiver units, with the acoustic resistance of such units being adjusted dynamically to an optimum value or within an acceptable range while the staking operation is in progress.

It is a further object of this invention to provide a new and improved apparatus for assembling disc-type acoustic resistors in associated frames of telephone transmitter and receiver units, which apparatus is of simplified, rugged and reliable construction, and is operated on a completely automated, high volume production line basis.

In accordance with one particular application employing a preferred method and structural embodiment of the invention, two porous, sintered metal acoustic resistors, in the form of discs, are fed to and loosely positioned within undercut, pre-formed apertures of a cylindrical frame comprising part of a carbon type telephone transmitter unit. Thereafter, the resistors are sensed under the control of a fluidic circuit for their presence and proper positioning, and then staked

within the associated apertures of the frame under a fluidically controlled staking force. This allows the value of acoustic resistance of the resistors to be dynamically adjusted simultaneously and in conjunction with the staking operation.

At the "sensing" station, air is supplied to the disc-type acoustic resistors previously seated in the transmitter frame through a pair of hollow tubes, the terminating ends of which respectively surround the pair of pre-formed apertures in the frame. The combined back pressure developed in both tubes is continuously monitored during the time each frame is located at the "sensing" station. If the resultant magnitude of the back pressure should indicate that one or both acoustic resistors are missing or are improperly nested within an associated aperture, that "sensed" condition is utilized as a control parameter to thereafter effect the ejection of that particular frame from the nest feeding conveyor.

At the "staking" station, hollow staking punches are utilized to supply air to the respective acoustic resistors previously mounted within the particular aligned frame, and the magnitude of the back pressure is again continuously monitored while at that station and during the staking operation. Significantly, the magnitude of this monitored back pressure is again utilized as a control parameter to determine the degree of force which should be applied to the staking punches. Advantageously, this permits the acoustic resistance of each resistor, or alternatively of a pair of resistors associated with each staking head in the illustrative embodiment, to be dynamically adjusted within very close limits, regardless of any physical variations that may exist between the porous disc-type resistors as manufactured.

In accordance with one preferred embodiment of the invention, the apparatus includes a nest feeding conveyor and an in-line array of operating stations including a frame loading station, a frame orienting station, a resistor loading station, a resistor pre-inspect (or sensing) station, a resistor reject-accept station, a resistor staking station and a staked resistor reject-accept station.

BRIEF DESCRIPTION OF THE DRAWINGS

FIG. 1, comprised of FIGS. 1A and 1B, is a plan view of the composite apparatus employed to initially position and then stake disc-type acoustic resistors in the frame of transmitter and/or receiver telephone units, and during the staking operation to simultaneously dynamically adjust the resistance of such resistors on an automated basis in accordance with the principles of the present invention;

FIG. 2 is an enlarged plan view of a portion of the frame loading station of the apparatus;

FIG. 3 is a sectional view of that portion of the composite apparatus depicted in FIG. 1A taken along the line 3—3 thereof;

FIG. 4 is a sectional view of that portion of the composite apparatus illustrated in FIG. 2 taken along the line 4—4 thereof;

FIG. 5 is a perspective view of a frame for a typical telephone transmitter unit having a central aperture and two mutually disposed apertures with undercut shoulders formed therein, and further illustrating two

disc-type acoustic resistors seated and staked within the outer apertures in accordance with the principles of the present invention;

FIG. 6 is a side elevational view, partially in section, of one of two identical mechanisms associated with the common frame orienting station for providing accurate rotational positioning of each frame within a nest after having been advanced thereto;

FIG. 7 is an enlarged, partial sectional view taken along the line 7—7 of FIG. 6, and discloses certain movable details of the operating head of one of the frame orienting mechanisms, and of the position thereof relative to a transmitter or receiver frame loosely positioned within a nest associated with the conveyor of the composite apparatus;

FIG. 8 is an enlarged, partial plan view taken along the line 8—8 of FIG. 7 of several nests and frames positioned on the conveyor, and illustrating in greater detail the structure of the conveyor;

FIG. 9 is a partial plan view of one of two identical mechanisms associated with the common acoustic resistor loading station, and illustrates, in particular, apparatus for feeding disc-type resistors to and properly positioning them within the respectively aligned undercut apertures of each transmitter or receiver frame advanced to that station in a nest of the conveyor;

FIG. 10 is a partial detail view of one of the two identical resistor loading heads;

FIG. 11 is a partial sectional detail view of one of the two feed tubes associated with a common resistor loading head after it has moved downwardly so as to position the terminating end of the feed tube coaxially of an aligned aperture in a frame, and further discloses a disc-type resistor, in phantom, being dropped by gravity feed downwardly through and toward the terminating end of the feed tube, and the same resistor in cross-section after having been seated in the frame;

FIG. 12 is a side elevational view, partially in section, of one of two identical mechanisms associated with the common resistor sensing (or pre-inspect) station, and particularly illustrates the apparatus for determining whether or not two acoustic resistors were fed to and properly positioned within the respective undercut apertures of each frame of a transmitter or receiver unit prior to having been advanced to the sensing station in accordance with the principles of the present invention;

FIG. 13 is a detail side elevational view, partially in section, illustrating the relationship between one sensing head frame, two seated acoustic resistors and an associated nest during a sensing operation;

FIG. 14 is a partial detail view in section of the apparatus employed at the resistor accept reject station, and which apparatus is duplicated at the staked-resistor accept-reject station;

FIG. 15 is a partial, side elevational view of one of two identical staking mechanisms associated with the common staking station, and particularly illustrates the apparatus utilized for driving a pair of staking punches downwardly against the frame of a transmitter or receiver unit so as to stake previously seated acoustic disc-type resistors within the aligned apertures of the frame;

FIG. 16 is a detail side elevational view of one staking punch, a portion of both the frame and the support-

ing nest aligned therewith, and of a resistor after having been staked within an aperture of the frame in accordance with the principles of the present invention;

FIG. 17 is a graph illustrating the differential pressure vs. flow-constant for a generator of the type embodied in the fluidic circuit of the present invention;

FIG. 18 is a schematic logic diagram illustrating in simplified form a constant-flow generator and the pressure sensing portion of the fluidic circuit associated with the sensing station;

FIG. 19 is a simplified schematic logic diagram illustrating certain of the basic fluidic devices and the functions performed thereby in the composite fluidic control circuitry embodied in the present invention;

FIG. 20 is a timing chart indicating when the various work stations are operated during the operating cycle;

FIG. 21 is a schematic diagram of the composite fluidic circuit which controls many of the operations performed by the composite apparatus at the various work stations in accordance with the present invention; and

FIG. 22, comprises of FIGS. 22A and 22B, is a schematic circuit diagram illustrating the composite fluidic circuit in greater detail, FIG. 22A illustrating the schematic circuitry associated with the two sensing (or preinspect) heads employed at the common sensing station, together with the cam-controlled sensors employed in conjunction with the composite circuit, and FIG. 22B illustrating the fluidic control circuits associated with the two staking-acoustic resistance adjusting heads, as embodied in the present invention.

DETAILED DESCRIPTION

Description of Product Assembled

In describing in greater detail the method of and apparatus embodied in the present invention, reference will be made to a specific manufacturing application involving the staking of disc-shaped acoustic resistors 26 (see FIG. 5) within pre-formed, undercut apertures 27 of a cylindrical frame 28 of either a telephone handset transmitter or receiver unit. One typical handset, for example, utilizes five acoustic resistors, two in the transmitter unit and three in the receiver unit.

The acoustic resistors are normally made of sintered stainless steel, and compressed into the desired shape under controlled conditions which are intended to result in all of the resistors exhibiting a consistent degree of porosity (or density) as manufactured. As previously mentioned, however, this result is hardly ever achieved in actual practice. Compounding the problem of controlling the porosity of the resistors, of course, is the necessity to stake them within the supporting frame. This staking operation has heretofore often resulted in the porosity dependent air flow resistance of the resistors varying appreciably, and in many cases beyond acceptable limits.

With respect to the transmitter frame 28, it is normally made of a zinc alloy, and has, in addition to the two resistor-receiving apertures 27, a larger central aperture 27a which accommodates a carbon filled transducer assembly (not shown).

When the acoustic resistors are staked within a transmitter frame (that combination generally being referred to as a T-1 bridge in connection with one par-

ticular type of telephone handset transmitter unit), very stringent acoustic resistance limits must be adhered to in order to insure that the particular transmitter (or receiver) unit will exhibit optimum acoustic output characteristics with satisfactory stability when the unit is completely assembled. The acoustic resistors are of particular importance in providing the proper acoustic damping effect for the particular transmitter or receiver unit when operated under all normal operating conditions.

OVERALL DESCRIPTION OF COMPOSITE MECHANICAL APPARATUS

Before considering the fluidic control circuit in detail, attention will first be directed to the details of the composite apparatus and, in particular, the sensing and staking stations thereof, which operate under the control of the fluidic circuit.

In accordance with one illustrative embodiment of the present invention depicted in FIGS. 1A and 1B, the composite apparatus 30 comprises a nest feeding conveyor 31 and an in-line array of operating stations including a frame loading station designated generally by the reference numeral 40, a frame orienting station 150, a disc-type acoustic resistor loading station 220, a resistor sensing station 270, a resistor reject-accept station 320, a resistor staking station 360, and a staked-resistor-frame reject-accept station 380. The entire apparatus is supported on a main base member 32.

FRAME LOADING STATION

Considering now in greater detail the frame loading station 40 best seen in FIGS. 1A and 2-4, transmitter frames 28 (FIG. 5), such as of the type employed in one particular telephone handset, are successively fed from either one of two conventional vibratory supply bowls 33a,b into an associated stationary feed track 34a,b.

Associated with the feed track 34a is a first cross-slide mechanism which comprises a first cam-operated cross-slide member 41 (see FIGS. 1A and 2) secured to a retractable drive rod 43. The drive rod is supported within a bore of and slidable relative to a stationary support block 45 which, in turn, is secured to a support member 46 of the apparatus. The end of the drive rod 43 opposite the cross-slide member 41 (see FIG. 1A) has a rotatable cam follower 47 secured thereto which biases against an eccentric cam 48 secured to a rotatable main cam shaft 51. The cam follower is spring biased against the eccentric cam 48 by means of a coil spring 53 which is supported at one end to the support block 45 and at the other end to the cross-slide member end of the drive rod 43.

A retractable nest-aligning pin 55 (best seen in FIGS. 2 and 3) is also supported within a bore of and slidable relative to a channel plate member 56 (FIG. 3). The nest aligning pin is secured through a coil spring 57 (FIG. 3) to a connecting rod 58, the latter being sup-

ported within and slidable relative to a bore extending through the support block 45 (FIG. 1A). One end of the connecting rod 58 has a rotatable cam follower 59 secured thereto, the latter being held in contacting relationship with a cam 61 secured to the drive shaft 51 by means of the coil spring 57. The function of the nest aligning pin will become more apparent hereinbelow in connection with a description of both the nests carried

by the conveyor and of the operation of the composite frame loading apparatus.

As best seen in FIG. 2, a spring-biased escapement mechanism 65 comprises a lever 66 secured to a bifurcated member 67, with the latter being pivotally secured to the channel plate member 56 of the apparatus by means of a pin 68. An adjustable contact member 69 is secured to the lower end of a lever 66. Upon retraction of the drive rod 43, the back edge of the cross-slide member 41 makes contact with the adjustable contact member 69 of the ejection mechanism. This causes the lever to pivot upwardly into a horizontal position, thereby compressing a coil spring 71 coaxially positioned about a pin 72 pivotally secured at its lower end to the lever 66 and at its upper end to a stationary bracket 73 of the apparatus.

As best seen in FIG. 2, when the lever is spring biased toward a nest 78, the nose portion 67a of the bifurcated member provides a temporary stop for the end frame 28a positioned in the associated stationary feed track 34. When the lever 66 is spring biased into a horizontal position, however, the nose portion 67a releases the end frame and the nose portion 67b momentarily functions as the stop for the next succeeding frame which is now the end one. Upon the lever of the escapement mechanism again being spring biased toward a nest, the nose portion 67a again functions as the stop for the end frame previously retained by the nose portion 67b.

Each frame upon being released by the escapement mechanism 65 is moved from the position designated 28a in FIGS. 1A and 2 to the position 28a' by gravity feed down the inclined portion 34a of the feed track. An L-shaped stop member 76, secured to a stationary support plate 77 (FIGS. 2,3) of the apparatus, is positioned in aligned relationship with the cross-slide member 41. As such, when the cross-slide is moved so as to transport a frame 28 from the position designated 28a' in FIG. 1A to the position designated 28a', the combination of the cross-slide member 41 and the stop member 76 results in the transported frame being accurately positioned within an aligned nest 78 of the conveyor, best seen in FIGS. 3 and 4. The inner frame confining edges of both the cross-slide member 41 and the stationary stop member 76 have undercut grooves formed therein so as to accommodate the projecting flange portion of the frame 28.

A second cam-operated cross-slide mechanism associated with the feed track 34b comprises a cross-slide member 81 (best seen in FIGS. 1A and 2) which is secured to a retractable drive rod 83 which, in turn, is supported within a bore of and slidably relative to a stationary block 85. The end of the drive rod 83 opposite the cross-slide member 81 is connected by means of a pin 86 to a rotatable cam follower 88 which, in turn, is held in contacting relationship with an eccentric cam 91 secured to the drive shaft 51. A coil spring 93, affixed at one end to the drive rod 83 and at the other end to the stationary block 85, maintains the cam follower in continuous contacting relationship with the cam 91.

A retractable spring-biased nest aligning pin 96 (FIG. 2), identical to the pin 55 previously described, is also supported within a bore of and slidably relative to the channel plate member 56 (FIGS. 2 and 3). The nest aligning pin 96 is secured through a coil spring (not shown but identical to the spring 57 depicted in FIG. 3)

to a connecting rod 97, the latter being supported within and slidably relative to a bore extending through the support block 85. One end of the connecting rod 97 has a rotatable cam follower 98 secured thereto, the latter being held in contacting relationship with a cam 99 secured to the drive shaft 51 by means of the aforementioned coil spring, not shown.

Associated with the cross-slide member 81 is a stationary stop member 105 (best seen in FIG. 2), the combination insuring that each successive frame 28 will be accurately positioned in an aligned nesting fixture 78 of the conveyor. Both the cross-slide member 81 and the stop member 105 have undercut grooves therein so as to accommodate the projecting flange portion of each frame 28. Cross-slide member 41, primarily associated with feed track 34a, also has an undercut groove along the edge nearest the stop member 105 so as to provide further confinement of a frame transported by the cross-slide member 81 into an aligned nest of the conveyor.

A second escapement mechanism 110 (FIG. 1A), which is constructed and operates in the same manner as the escapement mechanism 65 described hereinabove, is similarly pivotally mounted on the channel plate member 77 of the apparatus and successively releases frames 28 from the stationary guide track 34b in response to the reciprocal movement of the cross-slide 81.

CONVEYOR MECHANISM

As best seen in FIGS. 3 and 8, the conveyor 31 comprises two parallel extending link-chains 112, with a spaced array of the nests 78 supported therebetween. The intermediate shank portion of pins 113 of each chain-link rides along a slot 114 defined by two mutually disposed leg portions of mating rail blocks 115a and b associated with each chain (see FIG. 3). The two pair of parallel extending rail blocks are secured to a base plate 140. The link-chains engage a pair of sprocket wheels (not shown) at each end of a closed loop, with the downstream sprocket wheel being secured to a drive shaft 122 (FIG. 1B) which, in turn, is coupled through a chain drive coupler unit designated generally by the reference numeral 125 to a clutch unit 126. The clutch unit is connected through a gear reducer 127 to a composite motor-clutch-brake power source designated 129. As also best seen in FIG. 1B, the drive shaft 51 is chain-drive coupled to the clutch mechanism 126.

Each nest 78 of the conveyor, as best seen in FIGS. 3 and 8, comprises a substantially U-shaped block 135 which has a central bore extending therethrough and within which is positioned for slidable movement relative thereto a double-headed biasing member 137. Two additional bores are also formed in the U-shaped block 135, which bores respectively accommodate coil springs 138 and the head portions of the alignment pins 141.

The under-surface of the upper head portion of each biasing pin 137 normally makes contact with the two adjacent head portions of the orienting pins 138 as best seen in FIG. 3. The lower head portion of each biasing pin 137 rides within a groove formed by two juxtaposed stationary cam members 139, the latter being secured to the lower base plate 140 of the apparatus. The sta-

tionary cam members 139, only one of which is seen in FIG. 4, provide a means whereby the biasing pin 137 associated with each nest may be moved up and down relative thereto during longitudinal movement of the conveyor. Such movement of the pin 137, in turn, moves the spring-biased orienting pins 141 controllably into and out of the aligned apertures of a particular frame 28, previously positioned within an associated nest 78 of the conveyor. The reasons for such movement of the orienting pins will be discussed in greater detail hereinafter.

In order to insure accurate alignment of each nest at each work station, the U-shaped block 135 thereof is formed with a keying slot 135a in one side, and is secured to the chain conveyor through a pair of cylindrical members 143 (see FIGS. 3 and 8), each being secured to a separate bracket 145. Each bracket is, in turn, secured to a pair of pins 113 of and functions as a link of the chain conveyor. A pair of mutually disposed stop plates 146 (FIG. 8) are secured to the front and back sides of each nest block 135 relative to the directions of movement thereof. Limited spring-biased longitudinal movement of each nest block 135, relative to the cylindrical members 143 and the chain conveyor, is effected through the use of four coil springs 149. These springs are partially disposed within respective bores of the cylindrical members 145, and have their free ends biased against the stop plates 146.

Such spring-biased nest mounting permits each of the aforementioned nest-aligning pins 55 and 96, when advanced, to readily wedge into at least a partially aligned keying notch 135a of a nest block indexed thereto. The alignment pins thereby insure that each nest block is accurately positioned and rigidly clamped at the frame loading work station. As will be seen hereinafter, similar nest aligning pins are also employed at each of the other work stations.

FRAME ORIENTING STATION

Upon two frames 28 being positioned within two adjacent and respectively aligned nests 78 of the conveyor at the frame loading station 40, the conveyor is advanced the equivalent of two nest positions whereat, as depicted in FIG. 1A, the two most recently loaded frames are positioned at the frame orienting station 150. When the frames arrive at this station, the acoustic resistor-receiving apertures 27 pre-formed therein may or may not be aligned with the spring-biased alignment pins 141 associated with each nest 78. If a given frame should not be properly oriented, the apparatus at the frame orienting station is constructed to rotate either one or both frames advanced to that station until each frame is properly positioned relative to the orienting pins 141.

With particular reference now to FIGS. 6 and 7, and with respect to only one of two identical mechanisms associated with that station, a cam-actuated lever 151 is pivotally supported by a pin 152 which, in turn, is mounted on a U-shaped support bracket 153. The bracket is mounted on a support block 154 which, in turn, is secured to the stationary support member 46.

The lever 151 supports at one end an air motor 155 and at the opposite end a rotatable cam follower 157 which is maintained in contacting relationship with a cam 158 by means of a coil spring 161 supported

between the support block 154 and the lever 151. The air motor 155 has mounted on the shaft thereof a resilient pad assembly designated generally by the reference numeral 165. The pad assembly comprises a resilient circular pad 166, such as of rubber, which is supported by a circumferentially disposed array of fastening members 168 which extend through aligned apertures in a spacer plate 171 having a collar portion (as best seen in FIG. 7) which is secured by any suitable means to the shaft of the air motor 155. The pressure pad is spring biased by means of a coil spring 177 which is positioned between the pressure pad 166 and a recessed portion of the spacer plate 171.

A triangularly shaped cam follower support plate 187 is pivotally secured by a pin 188 to a bracket 191 affixed to the stationary support member 46. A cam follower 193 is rotatably secured to the plate 187 near one corner thereof, and continuously makes contact with a cam 195 (shown only partially by a dashed line in FIG. 6). Another cam follower 197 is also rotatably secured to the plate 187 and makes contact with a protruding spring-biased push button 198 of a microswitch 199. The microswitch, actuated in response to rotation of the cam 195, is employed to control the time during which the air motor 155 is operated. More specifically, the microswitch 199 operates a conventional solenoid actuated pneumatic valve MV1 which, in turn, controllably supplies air from a manifold MF1, depicted in FIG. 21, to the air motor 155.

Mounted for retractable movement within a passage of the support block 154 is a connecting rod 201. A cam follower 203 is rotatably secured to the rod 201 at one end, and is maintained in contact with a cam 204 (only partially shown by a dashed line) by means of a coil spring 205 which is partially supported within a bore of the support member 46 at one end and abuts against a stop member 206 secured to the driving rod at the other end. A coil spring 209, partially secured within a bore of the connecting rod at the forward end, biases against a nest aligning pin 211, the head portion of which is best seen in FIG. 8.

A stop member 213, secured to a forward nose portion of the connecting rod 201, extends into and is capable of travelling along a slot 214 in the aligning pin 211. Member 213 normally is spring-biased against the rearward end of the slot during the forward travel of the pin 211 unless an obstruction should be encountered by the latter. Pin 211, as in the case with pins 55 and 96 associated with the frame loading station (FIG. 2), projects through an aperture in the rail block 115b after each indexing of a nest into alignment therewith, and further wedges into the notched area 135a of the nest block 135 so as to accurately and firmly position the latter at that work station. As previously mentioned, all of the nests 78 are spring mounted relative to the conveyor 31 by means of the four coil springs 149 so as to facilitate the attainment of accurate nest positioning.

With respect to the operation of the frame orienting apparatus 150, the cam 158 (best seen in FIG. 6) initially effects pivotal movement of the lever 151 through the cam follower 157 so that the resilient pressure pad 166 connected to the air motor 155 makes contact with the upper surface of an aligned frame 28 supported by

a particular nest 78 indexed into aligned relationship with the air motor. Just prior to such contact, the microswitch 199 is actuated to in turn operate the air motor which causes the resilient pad to rotate the particular frame a sufficient number of degrees, which may be a fractional part of one revolution or several revolutions, until the spring-biased alignment pins 141 (see FIG. 3) associated with the particular aligned nest snap upwardly through the pre-formed acoustic resistor apertures 27 in the frame 28.

Normally after two or three revolutions of the resilient pad, the particular number of revolutions being readily controllable by either the cam 195, or by other independent timing means of conventional design, the spring-biased lever 151 is pivoted such that the air motor 155 and resilient pad 166 secured thereto are raised above the correctly oriented frame. During the period in which contact is maintained between the pressure pad 166 and a frame 28 aligned therewith, cam 204, through the cam follower 203 and the connecting rod 201, forces the aligning pin 211 into the notch 135a of the aligned nest.

RESISTOR LOADING STATION

Upon indexing of the conveyor two more nest positions, the nests previously located at the frame orienting station 150 are now positioned at an acoustic resistor-loading station designated generally by the reference numeral 220 (see FIG. 1B). As the resistor-loading apparatus associated with each of the two nests at this station is identical, the apparatus associated with only one nest will be disclosed in detail and described hereinafter. At this station, the acoustic resistor apertures 27 of each frame 28 are respectively aligned with two hollow acoustic-resistor feed tubes 222 (see FIGS. 9-11). These feed tubes are slidably supported within bores of a connector block 223 which, in turn, is secured to a pivotal lever 255 (see FIGS. 1B, 10).

As in the case of the lever 151 described hereinabove in connection with the frame orienting station, each lever 225 is pivoted about a pin 227 (FIG. 1B) supported on a support block 229. Block 229 is, in turn, secured to the stationary support plate 46 of the apparatus. As also seen in FIG. 1B, pivotal movement of each lever 225 is effected through a common cam follower 231 which is maintained in contacting relationship with a common cam 232 secured to the drive shaft 51. A coil spring, not shown but similar to spring 161 employed at the frame orienting station and depicted in FIG. 6, biases each cam follower 231 against the cam 232.

A pair of nest aligning pins, not shown but similar to the pins 211 depicted in FIG. 8, are employed at the disc loading station and are reciprocally moved by the respective connecting rods 234 illustrated in FIG. 1B. Each connecting rod is operated through a cam follower 235 and an associated cam 236, the latter being connected to the drive shaft 51.

Each hollow feed tube 222 at the disc loading station, as best seen in FIGS. 10 and 11, is mounted for spring-biased movement within an associated bore of the connector block 223 by means of a coil spring 237, with the relative displacement between the feed tube and the block being confined between two spaced stop members 239 secured to the feed tube. The lower end

of each feed tube comprises a tapered conical nose portion 241 (see FIG. 11) which is dimensioned so as to coaxially surround an aligned one of the two apertures 27 formed in each frame.

5 Acoustic disc-type resistors 26 are successively fed from a vibratory supply bowl 242 to an aligned frame 28 through the hollow feed tubes 222 (best seen in FIG. 9). An escapement mechanism, designated generally by the reference numeral 245, is utilized to feed only 10 one acoustic resistor down each feed tube 222 during each dwell period of the indexable conveyor.

The ejection mechanism 245 accomplishes this result through the utilization of a pair of pivotal levers 247 15 respectively associated with the two feed tubes 222. With reference to the apparatus associated with only one feed tube, as such apparatus is identical for the other feed tube, the lower lever in FIG. 9, for example, is pivotally secured at an intermediate point to a pin 248, the latter being secured to a stationary bracket 249. This lever is actuated by means of a piston of a pneumatic feed cylinder FC1 coupled to one end thereof by means of a pin 253. The opposite end of lever 247 is bifurcated and drives a pin 254 of a cross-slide 255 in a reciprocal manner, as illustrated by one 20 position of lever 247 and the associated cross-slide being shown in phantom in FIG. 9.

The cross-slide 255 has a notch 257 formed therein which is dimensioned to receive one acoustic disc-type 30 resistor 26 fed thereto by gravity feed from the feed track 244 of the supply bowl. Upon actuation of the lever 247 by means of the pneumatic cylinder FC1, an acoustic resistor deposited in the notch 257 of the cross-slide is transported by the latter to a position over 35 the upper end of an associated feed tube 222 whereupon it falls by gravity, as indicated in phantom in FIG. 11, to and within the aligned aperture 27 (FIG. 5) of a given frame 28.

40 In order to allow the resistors to be seated within the respective apertures of each frame indexed to the resistor loading station, the alignment pins 141 of each aligned nest are withdrawn downwardly into the nest block 135 while positioned at that station. This is accomplished with a cam member (not shown) which is identical to the one designated 139 in FIG. 4. As previously mentioned, this cam member causes the double-headed member 137 associated with each nest indexed to the resistor loading station 220 to force the alignment pins 141 downwardly by a distance sufficient to 45 present no obstruction with the apertures 27 of a given aligned frame 28, best seen in FIG. 10.

Primarily because of the area required for each resistor loading mechanism associated with a different aligned frame, the common resistor loading station 220 50 actually comprises two mechanisms of the type depicted in FIG. 9 separated by two nest positions as depicted in FIG. 1B. As such, while two frame-carrying nests 78 are positioned beneath each supply bowl 242 during each indexing dwell period, as illustrated in FIG. 1B, two acoustic resistors are actually fed to only one of the frames under each supply bowl. In order to load successive frames transported along the conveyor with acoustic disc-type resistors, the first supply bowl, as 55 seen in FIG. 1B, loads the first (or upstream) frame positioned therebeneath whereas the second vibratory bowl loads the second (or downstream) frame during

the dwell period between each indexing of the conveyor two nest positions.

LOADED RESISTOR SENSING STATION

Upon two acoustic disc-type resistors having been deposited (or at least time having been allowed for their being deposited) within the appropriate apertures of every frame passed through the resistor loading station, such loaded frames are indexed in adjacent pairs to an acoustic resistor sensing or pre-inspect station 270 (FIGS. 1B, 12 and 13). In accordance with the principles of the present invention, two sensing heads designated generally by the reference numeral 275 and respectively associated with a different resistor-loaded frame assembly, are employed in establishing and measuring the magnitude of back pressure developed as a result of a controllable amount of air being directed through the acoustic resistors of an associated frame. The particular magnitude of the measured back pressure is utilized in a fluidic circuit, to be described in greater detail hereinbelow, to sense whether or not all of the resistors of a given frame are present and if they are, to further sense whether or not they are properly positioned in the frame. This information is temporarily stored, in logic form, in the fluidic circuit and subsequently used as a control signal at a subsequent resistor-loaded accept-reject station 350.

Considering one of the two identical sensing heads 275 now in greater detail (FIGS. 12, 13), it includes two tapered conical members 277, each having an axial aperture extending therethrough which communicates with a different air passage 281 formed in a connector block 282. The air passages 281 are connected to a common inlet air line 285.

Each sensing head 275, through the connector block 283, is secured by any suitable means to one end of a pivotal lever 287. An intermediate region of the lever and one end of a member 289 are pivotally secured to a pin 291 which is connected to a bracket 293. The bracket, in turn, is connected indirectly to the common stationary support plate 46 through a support block 295.

The end of the member 289 opposite the pivot end has a cam follower 297 secured thereto which continuously contacts a lever-pivoting cam 298, and is held in spring-biased relationship therewith by means of a coil spring 299 interposed between the support block 295 and the lever 287. A coil spring 301, supported by a fastener 302, exerts a downward force on an intermediate region of the member 289 and a mating end region of the pivotal lever 287 so as to allow the lever to pivot relative to the member 289 should the sensing head 275 hit an obstruction in being lowered against an aligned frame.

A biasing pin 303, secured to and extending downwardly from the connector block 282, projects through the central aperture 26a in each frame 28 aligned therewith when the sensing head is moved downwardly against the frame. The pin 303 is employed to bias against the double-headed member 137 so as to, in turn, overcome the spring bias of the alignment pins 141 and thereby move the latter downwardly out of engagement with the acoustic resistor apertures of the frame. This is done to allow air to be directed through the acoustic resistors during the sensing operation.

In order to remove some of the downward force which would be exerted on the conveyor chain 113 by reason of the pin 303, successive nests 78 ride along a short longitudinal section of track, comprising two spaced members 304 which are secured at their lower ends to the support plate 140.

5 A nest aligning pin 305 is associated with each sensing head, and is actuated by a spring-biased connecting rod 306 which is positioned within a passage of 10 and slidable relative to the support block 295. One end of the rod 306 has a cam follower 307 rotatably secured thereto which continuously makes contact with a cam 308. The other end of the drive rod biases against a coil spring 309 which, in turn, biases against 15 the nest aligning pin 305. Pin 305 slidably extends through a bore formed in the common conveyor rail block 115b, and is utilized to accurately and rigidly position a given nest 78 in aligned relationship with respect to an associated one of the two sensing heads 275 at the sensing station 270.

20 A stop member 312, secured to the connecting rod 306, extends into and is capable of travelling along a slot 305a in the aligning pin 305. Member 312 normally is spring-biased against the rearward end of the slot 25 during the longitudinal movement of the pin in response to the cam-actuated movement of the connecting rod. A coil spring 313, partially positioned within a bore of the stationary base 46, continuously biases against a stop 315 secured to the connecting rod 306 so as to maintain the cam follower 307 in continuous spring-biased contact with the cam 308.

LOADED RESISTOR ACCEPT-REJECT STATION

35 After the sensing heads 275 have been operated in the allotted time under the control of the associated cams 298, the conveyor 31 is indexed two more nest positions. At this point, the two previously sensed or pre-inspected resistor-loaded frames in adjacent nests 40 are respectively aligned with apparatus comprising a loaded resistor accept-reject station designated generally by the reference numeral 320 (see FIG. 1B). The apparatus associated with only one of the two aligned nests at this station is shown in detail in FIG. 45 14, and includes a reject cylinder RC1, operated under the control of the fluidic circuit, a blast-off air line 321 and a chute 323. A rigid and clamped terminating end portion 321' of the air line is positioned adjacent to and directed toward one edge of a particular frame 28 when 50 elevated slightly above a normally supporting surface of the aligned nest. With the chute being positioned on the side of the frame opposite the air line portion 321a, an air blast directed at the elevated frame from the air line 321 will lift the frame from the nest and 55 deposit it in the chute. Air is supplied to each of the lines 321 from the feeder line 483 connected to the supply junction point 482 depicted in FIG. 21.

60 Each reject cylinder, such as RC1, is employed to elevate and thereby facilitate the removal of a defective frame from a given nest positioned at the accept-reject station. This is accomplished by the spring-return piston of the reject cylinder when operated moving upwardly the double-headed biasing member 137 of the aligned nest (best seen in FIGS. 3 and 4). This causes 65 the alignment pins 141, normally spring-biased against the upper head portion of the biasing member 137 to contact undercut shoulder portions 135b of the nest

block 135 (see FIG. 3). As a result, the pins 141 are withdrawn from the apertures 27 of the particular frame associated therewith as the member 137 moves to its uppermost position. With the frame in no way then being secured to the nest, it is certain that an air blast through line 321 will eject a defective frame from its associated nest into the aligned chute 323.

Whether a given reject cylinder is actuated or not, of course, depends upon whether or not there had been an unacceptable condition sensed at the sensing station, and signal information representative thereof stored in and subsequently used by the fluidic circuit. This could result, for example, if an acoustic disc-type resistor had either not been fed to and positioned within a particular aperture of a given frame at the resistor loading station or had been positioned in the aperture improperly.

In either case, prior to the conveyor being indexed two more nest positions to the resistor-staking station 360 (see FIGS. 1B and 15,16), the piston of the pneumatic cylinder RC1, for example, is allowed, by spring-return action, to move the double-headed biasing member 137 associated with each nest downwardly to its normal position. This again allows the spring-biased alignment pins 141 to extend partially into the acoustic resistor apertures of the respective frames, but not to an extent which would dislodge the previously positioned acoustic resistors supported therewithin.

RESISTOR STAKING STATION

At the resistor staking station 360, two pneumatically operated staking heads 351 (only one being shown in FIG. 15) each supports two hollow staking punches 353 (best seen in FIG. 16). The punches are dimensioned to surround and partially overlap the acoustic resistors positioned within the aligned apertures of the particular frame positioned beneath each staking head. The terminus ends of the punches are also slightly tapered inwardly so as to effect restricted cold flow of peripheral frame material, radially inwardly, to insure reliable securement of the resistors within the apertures of the frame.

Control over the amount of force exerted on the frame by the punches 353 is also very important because it directly affects the degree of compressive force exerted on the acoustic resistors, which force can change the porosity (or density) of the resistor material in a manner whereby the acoustic resistance thereof may be altered. The present invention takes advantage of this fact by continuously controlling the staking force exerted by the punches so as to dynamically adjust the value of acoustic resistance during the staking operation.

With reference to only one of the two identical staking heads 351, it is connected through a link 357 to one end of a pivotal lever 359, and is slidably supported within a stationary cross member 361. Member 361 is secured to a yoke 362 which, in turn, is secured to the support base 46 of the apparatus. The lever 359 is pivotal about a pin 363 secured to the yoke 362, with the end of the lever opposite the stake driving end being pivotally secured by a pin 364 and a linkage 365 to a piston 367 of a pneumatically operated spring-return cylinder SC1.

This cylinder is supported on the main base member 32 (FIG. 1B), and as will be described in greater detail

hereinafter, has air supplied thereto during each staking operation through an air line 368. Air is supplied to the cylinder only until sufficient time has lapsed for the piston 367 of the cylinder SC1 to effect sufficient driving force against the staking head to result in an aligned pair of acoustic resistors not only being staked to the frame, but acquiring the desired or optimum value of acoustic resistance. In order to ascertain when the desired value of acoustic resistance has been attained, a controlled amount of air is supplied through a common air line 374 to the pair of acoustic resistors associated with a common frame. The particular magnitude of back pressure established by the presence (or absence) of the acoustic resistors is then utilized as a control parameter in the fluidic control circuit.

More specifically, whenever a predetermined magnitude of measured back pressure is detected by the control circuit, that circuit cuts off the air supply to the air cylinder SC1, whereupon the driving piston 367 thereof retracts, causing the pivotal lever 359 to withdraw the pair of staking punches 353 from the frame of the receiver aligned therewith. The overall plan view of the levers 359, the associated air lines and the air cylinders SC1,SC2 is best seen in FIG. 1B.

Primarily because of the spacing required between the air cylinders SC2, and also because of the physical spacing required between acoustic resistors positioned in one particular type of frame, the two staking heads 351 comprising the common staking station 360 are actually separated by three nest positions as illustrated in FIG. 1B. It is to be understood, of course, that the particular spacing required will depend primarily upon the particular factors involved in a given application. The primary reason for separating the staking heads three nest positions rather than two, or four or more, for example, resides in the fact that the composite apparatus has been designed such that the conveyor drive system advances the conveyor two nest positions during each index cycle and, as such, in order to successively position unstaked frames under both staking heads, even though every frame passes beneath both staking heads, it is necessary to space the staking heads by an odd multiple of next positions.

As in the case with the frame loading station 40, the resistor staking station also has an elongated pair of juxtaposed cam members 377 (FIG. 15) essentially identical to those designated 139 depicted in FIG. 4. These cam members cause the double-headed biasing member 137 of each aligned nest 78 to spring bias downwardly the associated alignment pins 141 so as to allow the flow of air through the acoustic resistor being staked to the frame. In this manner, the total magnitude of back pressure developed by a pair of acoustic resistors being staked can be simultaneously monitored during each staking operation.

A nest aligning pin assembly, similar to those disclosed hereinabove with respect to the other work stations, is also associated with each staking head assembly. Only a connecting rod 378 and a cam follower 379 of each such assembly is illustrated in phantom beneath the levers 359 in FIG. 1B.

55 STAKED RESISTOR ACCEPT-REJECT STATION

Upon completion of a staking operation, the conveyor is indexed two more nest positions whereupon

the two nests previously aligned under the two separated staking heads are then respectively aligned with spaced apparatus associated with a common staked resistor accept-reject station 380. The apparatus associated with each nest at this station is essentially identical to that previously described in connection with the resistor loaded accept-reject station 350 (see FIGS. 1B and 14). As such, the apparatus includes, as illustrated in only FIG. 1B, an air line 321 positioned to terminate adjacent to and in alignment with a frame positioned on an aligned nest. Each air line 321 terminates on the side of the frame opposite a chute 323 so that an air blast through line 321 could effect the ejection of a particular defective frame from an associated nest. Such an air blast would be triggered as a result of an inadequate value of acoustic resistance having been previously measured during the staking operation, and this fact stored as signal intelligence in the fluidic circuit for subsequent use.

To facilitate the removal of a defective frame, a pneumatic reject cylinder (not shown but identical to the one designated RC1 in FIG. 14) is also employed at each nest location associated with the staked resistor station 380. This cylinder, responsive to the receipt of an air blast in the line 321, is utilized to move the double-headed biasing member 137 upwardly and thereby momentarily effect the withdrawal of the alignment pins 141 from the aligned apertures 27 of the frame.

Those frames with staked acoustic resistors that were found to be acceptable in accordance with the back pressure measurement performed during the staking operation, continue to be transported along the conveyor and are dropped from the respective nests by gravity into a chute 385 for storage in a suitable receptacle (not shown) positioned beneath the output end of the conveyor as depicted in FIG. 1B.

FLUIDIC CONTROL CIRCUITRY

Parameters of Acoustic Resistors to be Controlled

With the composite mechanical portion of the apparatus for automatically feeding the frames of transmitter (or receiver) units and acoustic disc-type resistors to be assembled therein into relative position, and thereafter staking the resistors within pre-formed apertures of the frame while simultaneously dynamically adjusting the acoustic value of resistance associated with the acoustic resistors, the manner in which such operations are fluidically controlled will now be described in greater detail.

As previously mentioned, the particular transmitter frame assembly disclosed herein, for use in a typical telephone handset, contains two acoustic disc-type resistors made out of sintered stainless steel. In this illustrative example, each acoustic resistor must exhibit a value of acoustic resistance which falls within a range between 57 and 123 acoustic ohms. At a flow of 14 cc's per second these maximum and minimum resistance values respectively compare to pressure drops across the resistors of 0.320 and 0.691 inches of water.

For purposes of having a unit of measurement for acoustic resistance (R), specified in acoustic ohms, an equation has been derived therefor which equates (R) to a ratio of pressure differential (P) in dynes/sq.cm., and volume flow (U), in cc's/second, as follows:

$$R = \Delta P/U$$

As almost all acoustic resistors exhibit non-linear characteristics, the value of (R) is more accurately defined by the following relationship:

$$R = \Delta P/U^a$$

where (U) approximately equals 1.1 to 1.2. However, for purposes of describing and understanding the present invention, acoustic resistance will simply be defined hereinafter by the more simplified relationship

$$R = \Delta P/U.$$

GENERAL DESCRIPTION OF FLUIDIC TECHNIQUE

In the design of the fluidic circuitry embodied herein, an immediate problem was presented as to how to not only economically and reliably generate the necessary 14 cc's per second flow of air through the resistors, but to maintain that pressure constant, regardless of the value of acoustic resistance exhibited by the resistors, and particularly, during the staking operation. Upon extensive investigation, it was found that the best approach to the problem was to utilize the critical or choked flow orifice type of fluidic control.

Briefly, in accordance with this technique, when two orifices (the lower one defined by an acoustic disc-type resistor in the present invention) are operated in series, with the upstream orifice operating in the critical, or choked flow region, the downstream orifice will not affect the flow rate through the system, even though the value of resistance of the downstream orifice may vary, as long as the resistance through the latter orifice does not become great enough to unchoke the upstream orifice. In accordance with the present application, it is imperative that only the pressure upstream of the upstream orifice be held constant, and that the upstream orifice size be held constant to insure constant air flow therethrough.

For the particular frame and acoustic resistors in question herein, it was decided to maintain the pressure upstream of the upstream orifice at 34.7 psia. For air, when the pressure on the downstream side of that orifice is less than 0.526 of the upstream pressure, the air flow becomes choked. Conversely, when the pressure on the downstream side of the upstream orifice is less than 18.25 psia, the upstream orifice will be choked. In no case will the specified acoustic resistance value of the downstream orifice, determined by an acoustic resistor itself, cause the pressure between orifices to be greater than 18.25 psia. This can readily be determined from well-known design information derived from and based on the general principles of fluid flow.

The equation required to determine the sharp edge orifice size of the upstream orifice so as to generate 14 cc/sec. air flow at the upstream pressure of 34.7 psia is as follows:

$$U = 141.9 \times 10^2 Y C_d d^2 (P \times \Delta P)^{.5}$$

where

$$U = 14 \text{ cc/sec}$$

$$Y = \text{expansion factor}$$

$$= 0.863 \text{ (estimated)}$$

$$C_d = \text{flow coefficient}$$

$$= 0.6 \text{ estimated}$$

$$d = \text{orifice diameter (in.)}$$

$$P = \text{upstream pressure (psia)}$$

$$\begin{aligned}
 &= 34.7 \text{ psia} \\
 \Delta P &= \text{pressure differential (psi)} \\
 &= 16.45 \text{ psi}
 \end{aligned}$$

Solving the above equation results in a required orifice size of $d = 0.0089$ inch.

FIG. 17 illustrates the differential pressure vs. flow curves for both orifices produced by a substantially constant flow generator. The total pressure drop across two acoustic resistors staked in the transmitter frame under consideration is about 20 psi, and the point of intersection of the two curves determines the flow through the system and the pressure drop across the individual resistors. It can be seen that quite a wide variation in pressure drop across the downstream acoustic resistors staked in the frame will not unchoke the upstream orifice and will yield 14 cc/sec. air flow.

Once the desired constant flow rate through each staked transmitter frame assembly has been established, the problem thereafter is to monitor the back pressure developed thereacross, as a result of the presence of the pair of acoustic resistors, and to sense when the resultant pressure differential builds up to approximately the midpoint of the range specified for the particular transmitter frame assembly involved, this midpoint being 0.5 inches H_2O for the one under consideration herein. When that point is reached, the staking punches are withdrawn from the frame in accordance with the principles of the present invention.

To monitor and sense this pressure differential, a standard fluidic Schmitt trigger, such as Model No. 190462, sold by the Corning Fluidic Products Division of the Corning Glass Works, is employed. Such a Schmitt trigger functions as an extremely sensitive analog-to-digital interface, and consists of three analog devices, providing three stages of proportional amplification, and two digital devices, comprising a flip-flop and a NOR gate. The amplification is used to bring the pressure being sensed up to a level which is capable of switching the two digital fluidic devices, the latter being used to provide a usable output signal in the composite fluidic circuit. The five devices comprising the Schmitt trigger are advantageously contained in a single laminated and fused glass block, consisting of five plates, with internal connections being provided between all of the devices. This has the advantage of eliminating the need for matching the inputs and outputs of the various devices.

By way of illustration only, FIG. 18 discloses the main pressure sensing circuitry associated with one of the two identical sensing heads 275. This sensing circuitry comprises a constant flow generator 401, high limit and low limit Schmitt triggers 403 and 404, respectively, and a critical or choked, standard flow needle valve orifice 408 connected to a common junction with the acoustic resistor defining orifice 26. A standard fluidic meter 407 is also shown also connected in the air line between the standard orifice 408 and the acoustic resistor 26. In all of the fluidic circuits disclosed herein, the various devices and elements are shown in standard symbolic fluidic logic form established by the National Fluid Power Association.

As also seen in FIG. 18, the external connections required to each Schmitt trigger comprise two power supply level inputs PS1, PS2, two control pressure inputs C_1 , C_2 , the latter functioning as a bias pressure input which allows the switch point to be adjusted, and

two pressure outputs 01, 02. The switch point of the trigger can also be adjusted by using a needle valve on the bias input C_1 , such as needle valve 408, or if a fixed switch point is desired, a fixed fluidic resistor can be used. In some of the more recent commercially available Schmitt triggers, there is only one pressure input port PS1, with the PS2 port being internally provided through a tap.

While a small amount of the air flow intended to pass through the resistors is diverted to and consumed by the inputs C_1 of the Schmitt triggers, based on published operating data supplied by the manufacturer of those devices, it is estimated that the air flow through the acoustic resistors is maintained relatively constant to within 3 percent.

SIMPLIFIED FLUIDIC CIRCUIT EMBODIMENT

With the construction, functions and significance of the choked flow fluidic orifice and the fluidic Schmitt trigger having been described, attention will now be directed to a simplified schematic logic circuit designated 450 in FIG. 19, which circuit lends insight into the significant control inputs and outputs and actual functions made possible with the composite detailed fluidic circuit of FIGS. 21-22.

In the simplified version of the fluidic circuit, only those fluidic devices which are controlled, directly or indirectly, by timed input signals are illustrated. As such, the Schmitt trigger circuits that actually monitor the magnitude of back pressure at the sensing and staking stations are not disclosed, nor are certain other fluidic devices and circuitry which serve auxiliary protective functions. A description of the mode of operation of each of the basic types of fluidic devices employed, and the manner in which they are interconnected and function selectively and collectively in a typical operating cycle, will be described in greater detail hereinafter in connection with the finalized version of the composite circuit disclosed in FIGS. 21, 22.

With these limitations in mind, the simplified circuit 450, applicable to only one of the two sensing heads and only one of the two staking heads, comprises four OR/NOR gates designated 451-454 respectively controlled by different input signals applied to the input ports thereof designated A-D. Gates 451-454, in turn, selectively control flip-flop FF456 and three additional OR/NOR gates 457-459. As will become more evident hereinafter, the latter four fluidic devices selectively either directly or indirectly control the operation of four additional OR/NOR gates 461-464 and a flip-flop FF465.

For now, it will suffice to state that this minimal number of fluidic devices, in response to control signals applied to the four basic inputs A-D, which are common to two identical sensing and two identical staking head fluidic circuits, will initiate and/or carry out the operative functions summarized as follows:

- 60 A = S_3 signal on — start staking operation
- B = S_4 signal off — time out staking operation
- C = S_1 signal off — inspect read (sense presence or absence of loaded resistors)
- D = S_2 signal — retract all reject cylinders and reset memory

In addition to the requirement that the fluidic circuit sense pressure differentials at four different points of

assembly in conjunction with the operation of the composite apparatus, the particular assembly application involved herein also requires that the fluidic circuit sense the main cam shaft of the apparatus in order to effect the critical timing relationship between the apparatus and the various control functions involved therewith. Accordingly, fluidic position sensors, designated S1-S4 in connection with the four inputs A-D depicted in FIG. 19, and set forth above, are used to generate fluidic clock signals for the particular application described herein. Such sensors are of a commercial type available, for example, from the Double A Products Company. These position sensors, described in greater detail hereinbelow, are generally referred to as "block-bleed" devices and function in a manner similar in principle to the technique used for sensing acoustic resistance herein. More specifically, a change in back pressure caused by the presence or absence of a cam lobe signals the particular fluidic sensor at the proper time. Advantageously, constant air flow is not required through the position sensors since the operation thereof is not as stringent as in connection with the operation of the Schmitt triggers.

Having described the various functions of the four basic and common inputs associated with one sensing or pre-inspect and one staking head circuit in FIG. 19, attention will now be directed to the three outputs designated X-Z associated with that circuit. It is to be understood, of course, that these three outputs are duplicated for the fluidic circuitry associated with the other preinspect and staking heads, and that the resultant total of six pressure outputs are all employed to operate air cylinders controlled by fluidic piloted valves.

The functions of the three outputs X-Z illustrated in FIG. 18 can be summarized as follows:

X = staking head down

Y = staked resistor reject cylinder actuated if staked resistor-frame exhibits unacceptable value of acoustic resistance

Z = sensed resistor reject cylinder actuated if loaded resistor is absent from or improperly seated in the intended preformed aperture of the frame

PREFERRED DETAILED EMBODIMENT OF COMPOSITE FLUIDIC CONTROL CIRCUIT

With respect to the finalized composite fluidic control circuit 475, it is shown in the interest of clarity in FIG. 21 without any internal connections between the various fluidic devices. The complete circuit is disclosed in detail in FIG. 22, comprised of FIGS. 22A and 22B.

As illustrated in FIG. 21, a fluid medium, in the present application air, is supplied from an external source (not shown), which may comprise a pump or a compressor, through a valve 476 to a junction point 478, from which a branch channel 479 supplies air to a manifold MF1. A pair of filters F1 and F2, with a regulator R1 interposed therebetween, are preferably connected in series relationship within the branch channel 479. The filters are primarily employed to minimize the possibility of dust and, in the particular illustrative embodiment, F1 and R1 together comprise a Norgren adjustable filter which is capable of filtering out dust down to a particle size of five microns. Filter F2 com-

prises a commercially available Del-Tec filter. A pressure meter M1 is also coupled to the regulator R1 so as to allow visual monitoring of the input air pressure to the manifold, which pressure for the application under consideration herein is 40 psi.

The manifold MF1 has six output ports, each associated with a different pressure regulator designated R2-R7 of conventional design. As indicated, each of the regulators is adjusted to reduce the input pressure applied thereto (40 psi) to a desired output pressure. The outputs of the respective regulators supply air either directly or indirectly at the reduced levels through associated channels, and in the case of regulator R2, through an additional manifold MF2, to the various appropriate inputs of the fluidic devices comprising the composite fluidic circuit.

In one preferred illustrative embodiment, regulation is provided with Moore Products regulators, with regulator R4, operating with a low pressure equated to approximately 16.25 inches of H₂O, supplying air through a channel 507 to the low pressure supply ports of the Schmitt triggers ST1-ST8 and regulator R3, operating with approximately 1 1/4 psi pressure, supplying air through a channel 508 to the high pressure supply ports of those triggers. The supply ports of the remaining fluidic devices (and the position sensors, S1-S4, FIG. 22A), are selectively supplied with air of approximately 3 psi from regulator R6 and 5 psi from the regulators R5 and R7. As previously mentioned, regulator R2 supplies air at a pressure of 20 psi through a channel 509 to the manifold MF2, and regulator R5 also supplies air at a pressure of 5 psi to a manifold MF3, FIG. 22A.

In addition to the above-described high and low level pressure supply ports, all of the Schmitt triggers ST1-ST8 also have two input control ports C₁ and C₂. The C₁ ports of the triggers ST1 and ST2, associated with one of the two sensing heads 275, for example, are connected through a channel 512 and a needle valve NV1 to the manifold MF2, whereas the C₂ ports thereof are connected through respective needle valves NV5-NV6, channel 507 and regulator R4 to the manifold MF1. Similarly, the C₁ ports of Schmitt triggers ST3,ST4, associated with the other sensing head 275, are connected through a common channel 513 and needle valve NV2 to the manifold MF2, whereas the C₂ ports of these triggers are connected through respective needle valves NV7,NV8, common channel 508 and regulator R4 to the manifold MF1.

With respect to the four Schmitt triggers ST5-ST8 associated with the two staking heads 351, they are connected, as previously mentioned, to the manifolds MF1 and MF2 in a manner similar to that described above with respect to triggers ST1-ST4. The only difference is that input ports C₁ of the triggers ST5 and ST6 are connected through a common channel 514 to a needle valve NV3 to the manifold MF2, whereas the input ports C₁ of triggers ST7 and ST8 are connected through a common channel 515 and a needle valve NV4 to the manifold MF2. As for the control ports C₂ of the triggers ST5-ST8, they are respectively connected through needle valves NV9-NV12, common channel 507 and regulator R4 to the manifold MF1.

Needle valves NV5-NV12 respectively associated with the input control ports C₂ of the fluidic triggers ST1-ST8 permit the input bias pressures applied to

each associated trigger to be adjusted so as to allow the particular magnitude of input control pressure at which each such device will switch from one operating state to the other to be preset, thereby allowing control ranges to be established for each associated pair of triggers. Thus, with respect to the particular application involved herein, the only difference of significance from an operating standpoint between the Schmitt triggers ST1 and ST2, for example, is that the pressure of the input signal applied to the input control port C₂ of ST1 is set at a lower limit than C₂ of ST2. This permits an acceptable range of measured back pressure to be established for each frame being sensed for the presence and proper positioning of all of the acoustic-disc type resistors which should have been seated in the respective apertures thereof upon the resistor-loaded frames being indexed beneath a given one of the two sensing heads 275.

Also depicted in FIG. 21 are four three-way spring return reject valves designated RV1-RV4 and their respectively associated reject cylinders designated RC1-RC4. Reject cylinders RC1 and RC2 constitute part of the apparatus utilized at the resistor-loaded frame accept or reject station 350, only one being shown in FIG. 14. Reject cylinders RC3 and RC4 constitute part of the apparatus utilized at the staked-resistor accept or reject station 380. As the apparatus at this latter station is identical to that utilized at the resistor-loaded frame accept or reject station 350 disclosed in detail in FIG. 14, reject cylinders RC3 and RC4 are not separately shown in the apparatus drawings.

All of the other fluidic devices of the composite circuit 475 illustrated in FIG. 21 are comprised of fluidically operated OR/NOR gates, bi-stable flip-flops, and a one one-shot multivibrator. They are all characterized by having only single input supply ports which are selectively connected to one of the three pressure regulators R5, R6 and R7 coupled to the manifold MF1, shown only in FIG. 21. In FIGS. 22A and B, the fluidic device supply ports are correlated by like reference numerals with and shown detached from the regulators connected to manifold MF1. The remaining interconnections to and between the various fluidic logic devices, and the interconnections between certain of these devices and the output ports of the eight Schmitt triggers ST1-ST8, can perhaps best be understood by incorporating a description thereof with a description of the typical mode of operation of the composite circuit.

FLUIDIC "SENSING" CIRCUITRY

Attention therefore will now be directed first primarily to that portion of the composite circuit denoted within the dashed line 503 of FIG. 21, which circuitry is associated with the two sensing or pre-inspect heads 275 and the associated resistor-loaded frame accept or reject apparatus, all disclosed in greater detail in FIG. 22A.

In the latter figure, it is seen that six indicators designated I₁-I₆ are either directly connected to the four Schmitt triggers ST1-ST4, or indirectly connected thereto, such as the indicators I₃ and I₆ being indirectly coupled to Schmitt triggers ST2 and ST4 through fluidic OR/NOR devices designated O/N1 and O/N6,

respectively. These indicators preferably are of the spring-return, pneumatically operated conventional type having color coded piston ends which provide visual indications of a particular operating state of the circuitry to which they are selectively responsive. It should be remembered hereinafter that all of the indicator I₁-I₆ exhibit the particular green or red colors designated in the drawing when no pressure is applied to the composite circuit, in other words, when the composite circuit is disconnected from all fluidic power sources.

Also associated with the composite fluidic circuit as illustrated in FIG. 22A is a set of five cam-operated fluidic sensors of conventional design which are designated generally as S1-S5. The cams of these sensors are connected to a common shaft as indicated by the dashed line 517 extending through the centers thereof, and are contained within the housing designated fluidic timing cams illustrated in FIG. 1B. These cams are chain driven off the main drive shaft 51 of the apparatus. The functions of and the timing sequence of the cams of the sensors S1-S5 are illustrated in the timing chart of FIG. 20.

To facilitate a better understanding of the significance and functions of the various fluidic devices and of the mode of operation of the composite fluidic circuit, as a starting point assume that the conveyor 31 has indexed two nests 78 with frame-resistor assemblies respectively loaded thereon beneath the respective sensing or pre-inspect heads 275 (FIGS. 1B, 12 and 22). At that point in the operating cycle the pair of cams 298 and the associated cam followers 297, upon rotating, spring bias the pivotal levers 287 respectively associated with the sensing heads 275 downwardly toward the two aligned resistor-frame assemblies. Upon the lower tubular portions 277 of each sensing head (see FIG. 12 making contact with an aligned frame, air supplied from the manifold MF2 through the needle valve NV1 and channel 512 to the input control ports C₁ of Schmitt triggers ST1 and ST2 (FIGS. 21, 22A), for example, results in a back pressure being established in the channel 285.

This back pressure, if increased to a level above the predetermined lower limit setting of the Schmitt trigger ST1, as sensed at the input control port C₁ thereof, will cause that trigger to switch operating state, i.e., switch from the output port 01 to the output port 02. If this is done, pressure is supplied to the indicator I₁ so as to turn that indicator off. It is to be understood that in making reference to the pneumatically operated indicators herein, the expression "off" or "on" simply means that the indicator has been actuated in such a way that a particular color associated with that indicator provides a visual indication of either an "on" or "off" condition.

As for the Schmitt trigger ST2 coupled to the common sensing head 275, if the back pressure established and sensed at the input control port C₁ of that trigger does not exceed an upper predetermined limit, it will not switch operating state from the 01 to the 02 output port. As such, if the sensed resistor-loaded frame assembly associated with a given sensing head 275 produces a magnitude of back pressure within an acceptable range, a fluidic pressure signal will continue to be supplied through the output port 01 of the trigger

ST2 to the indicator I_2 and, thereby, remove a "High Red" indication from that indicator.

Under these operating conditions, it is seen that no fluidic signal will be supplied from the output port 01 of the trigger ST1 through a channel 519 to the input control port C_3 of an OR/NOR gate O/N1. Likewise, no fluidic signal will be supplied from the output port 02 of the trigger ST2 through a channel 520 to the input control port C_1 of the same gate O/N1. Hereinafter, in the interest of brevity, the air generated fluidic input control signals and output signals associated with the various fluidic devices will simply be referred to as input and output signals. In the case of timed control signals supplied from the sensors S1-S5, when such signals are of zero magnitude, they will be indicated as such.

With no input signal being applied to either the input control port C_1 or C_3 of the gate O/N1, indicative of an acceptable resistor-loaded frame assembly having been sensed, an output signal would be produced at the output port 02 thereof, and would be directed through a channel 531 to the input control port C_1 of a gate O/N3. This input signal, in turn, would result in an output signal being exhausted to atmosphere through the output port 01 of the gate O/N3. As such, no signal would be produced at and directed from the output port 02 of the gate O/N3 through a channel 539 to an input control port C_1 of a flip-flop FF1. Assuming at present that this flip-flop had previously been reset to produce an output signal at the port 02 thereof, such an output signal would continue until at least the next "Inspect-Read" period of the subsequent operating cycle.

Accordingly, an output signal would be directed through a channel 541 to an input control port C_1 of a gate O/N5. Such an input signal applied to that gate would therefore produce an output signal, independent of whether or not an input signal was concurrently applied to the input control port C_3 of the flip-flop FF1, which would be exhausted to atmosphere at the output port 01 thereof. Thus, in the case where the Schmitt trigger ST1 switched operating state as a result of a minimum predetermined value of back pressure having been established during the sensing or "Inspect-Read" period of one operating cycle, there could be no signal directed from the output port 02 of the gate O/N5 to the reject valve RV1 during the subsequent "Reject" period. This assumes, of course, that the high limit trigger ST-2 would not have switched operating state during the sensing period in question.

Considering the input control port C_3 of the gate O/N3 more specifically now, it is connected through a channel 534 to the output port 01 of the gate O/N2. An input control port C_1 of that gate is, in turn, connected through a channel 537 to the sensor S1. This sensor, during the period designated "Inspect-Read" in the timing chart of FIG. 20, applies a control signal of zero magnitude to the input control port C_1 of the gate O/N2. As such, there is no output signal momentarily directed through the channel 534 to the input control port C_3 of the gate O/N3.

As previously mentioned, the absence of a signal at the input control port C_3 is of significance only if no input signal is applied to the input control port C_1 of the gate O/N3, which condition would result if the Schmitt trigger ST1, for example, did not switch operating state during the "Inspect-Read" period. The absence of

input signals at both input control ports of the gate O/N3 is thus indicative of an unacceptable resistor-loaded frame assembly having been sensed, and would arise as follows:

5 If the Schmitt trigger ST1 should not have switched operating state during the "Inspect-Read" period, an output signal would have been produced from the output port 01 thereof and directed through channel 519 to the input control port C_3 of the gate O/N1. As such, there would have been no signal supplied through channel 531 to the input control port C_1 of the gate O/N3. If an input signal was concurrently absent at the input control port C_3 of the gate O/N3, which would be the case during the "Inspect-Read" period, an output signal would be produced at the output port 02 of that gate and directed through channel 539 to the input control port C_1 of the flip-flop FF1. This input signal would cause the flip-flop to switch operating state so as to remove an output signal from the port 02 thereof. As such, no signal would be directed through channel 541 to the input control port C_1 of the gate O/N5, indicative of an unacceptable resistor-loaded frame assembly. If an input signal was concurrently absent at the input control port C_3 of the gate O/N5, the reject valve RV1 would then be actuated. As will now be described, the absence of a signal at the input port C_3 occurs once each cycle during the "Reject" period.

More specifically, sensor S3 during the short "Reject" period supplies a fluidic pressure signal through channels 557 and 555 to the input control port C_1 of a gate O/N9. During the application of such an input signal, no output signal is produced at the output port 02 of the gate O/N9 and, as such, no signal is directed through channels 553 and 551 to the input control port C_3 of the gate O/N5. Accordingly, it is seen that if no input signal is applied to either of the input control ports C_1 or C_3 of the gate O/N5 during the "Reject" period, an output signal would be produced at the output port 02 thereof, which signal would then actuate the reject valve RV1 and, in turn, the reject cylinder RC1 associated therewith. One of these cylinders is depicted in FIG. 14 as part of the resistor-loaded frame accept or reject station 350.

It is thus seen that the function of the sensor S3 and the gate O/N9, in combination, is to not only establish a "Reject" signal, but to delay the actuation of the reject valve RV1 from the termination of the short "Inspect-Read" period of one particular operating cycle through almost the entire indexing period of one particular operating cycle through almost the entire indexing period of the conveyor during the succeeding cycle (see timing chart FIG. 20). This delay is necessary so that any resistor-loaded frame assembly that had been found to be unacceptable during any given operating cycle would not be ejected from the nest thereof until the conveyor had indexed that nest and sensed assembly from the sensing station 270 (FIG. 1B) to the accept or reject station 350. Such delay in ejection is dictated only because of space limitations imposed by the particular apparatus and application embodied herein.

65 After the "Reject" period has elapsed during a given operating cycle, a momentary fluidic "Eliminate Memory" signal (zero magnitude), established by the sensor S2, is applied to the input control port C_1 of a

gate O/N4 through a channel 549. This results in an output signal being produced at the output port 02 of the gate O/N4 and directed through channels 547 and 544 to the input control port C_2 of the flip-flop FF1. This momentary signal resets the flip-flop or, in other words, effectively erases the information previously stored therein, as represented by its previous operating state. The flip-flop FF1 is thus placed in an operating condition in preparation for the sensing of a new resistor-loaded frame assembly indexed under a particular one of the sensing heads 275.

Should a given assembly establish a magnitude of back pressure great enough to switch the operating state of the Schmitt trigger ST2 during the "Inspect-Read" period of the operating cycle, an output signal would be produced from the output port 02 thereof and applied through channel 520 to the input control port C_1 of the gate O/N1. This input signal, of course, would result in no signal being directed through channel 531 to the input control port C_1 of the gate O/N3. With no signal appearing at the input control port C_3 of that gate either during the "Inspect-Read" period, an output signal from the port 02 of the gate O/N3 would be directed through the channel 539 to the input control port C_1 of the flip-flop FF1 so as to switch the operating state thereof to produce an output signal at the port 01. As previously described, this results in no signal being applied to the input control port C_1 of the gate O/N5, and with a signal also being absent from the C_3 input control port during the "Reject" period of the subsequent operating cycle, controlled by sensor S3, the particular resistor-loaded frame assembly that was previously sensed and found defective would be ejected upon the actuation of the reject valve RV1. It is also seen that upon the switching of the Schmitt trigger ST2, there would be no output signal produced at the output port 01 of the trigger ST2 to remove the "High Red" indication from the indicator I_2 .

From the foregoing description of the sensing or pre-inspect fluidic circuitry, it can thus be seen that the absence of a fluidic pressure signal at the input control port C_1 of the flip-flop FF1, for example, is indicative of an acceptable resistor-loaded frame assembly having been sensed by the associated sensing head 275 and the Schmitt trigger circuits ST1, ST2, whereas the presence of such a signal at the input port C_1 of that flip-flop is indicative of an unacceptable assembly. However, it should be noted that the presence of the latter signal will not directly effect the actuation of the reject valve RV1, as the momentary absence of a signal at the input control port C_3 of the gate O/N5 is also required. The presence or absence of a signal at the port C_3 , of course, is dependent on the operating state of the gate O/N9 which is, in turn, controlled by the "Reject" sensor S3.

As the fluidic circuitry associated with the other sensing head 275 is identical to that described hereinabove, no further description of the mode of operation involved therewith is believed necessary. Structurally, the duplicate circuitry comprises the two Schmitt triggers ST3 and ST4, together with the gates O/N6-O/N8 and the flip-flop FF2. It is to be understood, of course, that the input control port C_2 of the flip-flop FF2 and the input control port C_3 of the gate O/N8 are respectively controlled through the same

gate O/N4-sensor S2 and gate O/N9-sensor S3 combinations that are employed with and which were described hereinabove in connection with the operation of flip-flop FF1 and the gate O/N5.

With reference back to the simplified fluidic control circuitry of FIG. 19, it is readily seen that the devices therein are common to those depicted in FIG. 22A as follows: 453 to O/N2, 454 to O/N4, 458 to O/N3, 459 to FF1 and 464 to O/N5.

FLUIDIC "STAKE" CIRCUITRY

Having described the operation of the fluidic circuitry associated with the sensing heads 275 and the related resistor-loaded accept-reject apparatus, attention will now be directed to the fluidic circuitry associated with the staking apparatus and the staked-resistor accept or reject circuitry denoted within the dashed line 504 in FIG. 21. This circuitry is illustrated in greater detail in FIG. 22B.

Inasmuch as the fluidic circuitry associated with Schmitt triggers ST5 and ST6 in FIG. 22B is duplicated with respect to the Schmitt triggers ST7 and ST8, the description which follows will be confined only to that circuitry associated with the triggers ST5 and ST6. As in the case with the Schmitt triggers ST1-ST2 relating to one half of the sensing or pre-inspect circuitry described in detail hereinabove and depicted in FIG. 22A, it is seen that each of the fluidic Schmitt triggers ST5-ST6 has two input supply ports designated R3, R4, which are respectfully connected through the channels 508 and 507 (FIG. 21) to the regulators R3 and R4 associated with the manifold MF1. Both triggers ST5 and ST6 also have two input control ports C_1 and C_2 , the ports C_1 being connected through channel 514 (FIG. 21) and needle valve NV3 to the manifold MF2, and the ports C_2 being connected through a needle valve NV9 and channel 508 to the regulator R4 of the manifold MF1.

As schematically shown in FIG. 21, the input control ports C_1 of the Schmitt triggers ST5-ST6 are each directly coupled to a common one of the two staking heads 351, partially shown in symbolic form. The only difference of significance from an operating standpoint between the Schmitt triggers ST5 and ST6 is that the pressure input applied to the input port C_2 of the trigger ST5 is set at a lower limit.

The needle valves associated with the control ports C_2 of the triggers ST5-ST6, such as needle valve NV9, for example, permits adjustment of the pressure which controls the point at which the trigger ST5 associated with that valve will switch from one stable state to the other.

Two output ports identified by the numerals 01 and 02 are associated with each of the Schmitt triggers ST5-ST6. The circuits connected to these output ports and the functions performed thereby will be discussed in greater detail hereinbelow in connection with the operation of that portion of the fluidic staking circuitry associated with the staking head 351 coupled to Schmitt triggers ST5 and ST6.

As depicted in FIG. 22B, two indicators I_7 and I_8 are directly and respectively connected to the Schmitt triggers ST5 and ST6. These indicators, as in the case with those employed in the sensing of pre-inspect circuitry, preferably are of the spring-return pneumatically

operated type having color coded piston ends which provide visual indications of a particular operating state of the circuitry with which they are selectively and responsively associated.

As a starting point of reference, it should be remembered hereinafter that the indicator I_7 (as well as I_9) normally is off, i.e., no color, such as red for example, is indicated when there is no fluidic pressure signal applied thereto, whereas the indicator I_8 (as well as I_{10}) is on, i.e., a color such as green is indicated when no fluidic pressure signal is applied thereto.

In a typical operating cycle, the staking fluidic circuitry depicted in FIG. 22B receives an initiating "Stake" signal from the sensor S3 (FIG. 22A) through channel 557 to the input control port C_1 of a gate 0/N10. This occurs each time that the conveyor indexes two resistor-loaded frames 28 beneath the respective staking heads 351 (FIGS. 1B, 15, 16 and 22B). The sensor signal produces an output signal at the output port 01 of the gate 0/N10. The latter signal is directed through several channels at this point, one being through a channel 581 to the input control port C_1 of a flip-flop FF3. In response to such an input, the flip-flop normally would produce an output signal from the output port 01 thereof through a channel 583 to the pneumatic staking valve SV1. Actuation of that valve, in turn, causes the associated pneumatic staking cylinder SC1 (FIG. 21) to pivot the lever 359 supporting an associated staking head 351 (see FIG. 15) downwardly so that the staking punches 353 of the staking head contact the frame aligned therebeneath.

While the staking head is moving downwardly, fluidic air pressure is continuously supplied to not only the input supply ports of the triggers ST5-ST6 from the regulators R3 and R4 associated with the manifold MF1, but fluidic pressure is also being supplied to the input control ports C_1 and C_2 of these triggers from the manifolds MF2 and MF1, respectively. It should be remembered that the respective input control ports C_1 of the Schmitt triggers ST5-ST6 are also directly coupled through different common channels 374 to the associated staking heads 351. As a result, upon the tubular end portions of the staking punches 353 (FIG. 16) contacting the respective frames aligned therebeneath, a back pressure is established at the input control ports C_1 of the Schmitt triggers ST5-ST6.

If this back pressure increases to a predetermined lower limit as the staking operation progresses, because of the staking punches compressing the acoustic resistors 26 (FIG. 5) slightly during the staking operation, the Schmitt trigger ST5 would switch operating state, whereby an output signal would be produced at the output port 02 rather than at the input port 01 thereof. As such, no fluidic pressure would be applied to the "normally off" indicator I_7 , which would therefore reveal that the staked resistor-frame assembly had exhibited a value of acoustic resistance above a predetermined minimum limit upon the commencement of a staking operation. The point at which the low limit Schmitt trigger ST5 would switch operating state is, of course, preset by adjustment of the needle valve NV9 controlling the bias pressure applied to the input control port C_2 of that trigger.

If the Schmitt trigger ST6 should also switch operating state during the normal "stake down" period, that

would indicate that the staked resistors in a given frame assembly had reached the midpoint value of an acceptable range of acoustic resistance.

TWO OPERATING CIRCUIT CONDITIONS INDICATIVE OF ACCEPTABLE ASSEMBLIES

Thus there are two operating conditions under which staked resistor-frame assemblies will be found acceptable. The first condition indicative of an acceptable resistor-frame assembly would result if the sensed back pressure rises sufficiently within a prescribed time-out period to at least switch the low limit Schmitt trigger ST5 from the 01 to the 02 output port. The second condition would occur if the sensed back pressure rises to a magnitude sufficient to switch the operating state of not only the low limit trigger ST5 initially, but the mid-limit trigger ST6 thereafter within a predetermined period of time. If the latter trigger is switched, it would indicate that the staked resistor-frame assembly had reached a desired midpoint value of acoustic resistance during the staking operation.

FIRST CIRCUIT CONDITION — ACCEPTABLE

In the first operating condition where only the Schmitt trigger ST5, for example, switches operating state within a predetermined, cam-controlled time-out period, a stake time-out circuit is employed to effect not only the retraction of the associated staking head 351, by removing fluidic pressure from the associated pneumatic staking valve and cylinder, such as SV1 and SC1, but to effect the prevention of the actuation of the related reject valve RV3 during the reject period of the subsequent operating cycle. This time-out circuit includes a sensor S4 (FIG. 22a) and a gate 0/N11 utilized in conjunction with a flip-flop FF4 and a variable one-shot multivibrator ST9. The function and significance of the multivibrator ST9 will be discussed in greater detail hereinafter in connection with the fluidic circuit operating conditions indicative of unacceptable resistor-frame assemblies.

Upon the low limit Schmitt trigger ST5, for example, switching operating state, an output signal would be produced at the port 02 thereof. This signal would then be transmitted through a channel 585 to an input control port C_1 of a gate 0/N13. This, in turn, would result in an output signal being produced at the port 01 of the gate 0/N13, and directed through a channel 587 to the input control port C_1 of a gate 0/N14. The presence of a signal at the port C_1 would result in an output signal being exhausted to atmosphere from the output port 01. In that case, there would be no output signal transmitted from the output port 02 of the gate 0/N14 through a channel 589 to an input control port C_3 of a flip-flop FF5.

Assuming for the moment that no signal would likewise be present at the input port C_1 of the flip-flop FF5, it would remain in its previous reset condition, thereby producing an output signal at the port 02 thereof. The manner in which the flip-flop is reset during each operating cycle will be described hereinbelow. With a signal produced at the output port 02 of the flip-flop, it would be directed through a channel 615 to the input control port C_3 of a gate 0/N15, resulting in an output signal being exhausted to atmosphere through the port 01 thereof, thereby preventing the reject valve

RV3 from being actuated, at least until after an "Eliminate Reject Memory" signal would be applied to the flip-flop during the subsequent operating cycle. As such, the receipt of a zero input signal at the input control port C_1 of the latter gate during the "Reject" period of the subsequent operating cycle would have no effect on actuating the reject valve RV3.

It should be remembered that as in the case with the flip-flop FF1 and FF2 employed at the sensing station, the flip-flop FF5 (and FF7) are employed as temporary memory storage devices. More specifically, during the staking period, the flip-flop FF5, for example, will either receive no input signal, one input signal or two input signals depending on whether the staked resistor-frame assembly was determined by the fluidic circuitry to be acceptable or not.

Prior to the generation of any such signals during each operating cycle, however, a zero "Eliminate Reject Memory" signal, supplied from a sensor S2, would be directed through a channel 549 to an input control port C_1 of the gate 0/N4 (depicted in the sensing circuitry of FIG. 22A). As a result, that gate would momentarily switch operating state to the output port 02 thereof and provide a signal through channel 549 to the input control port C_2 of the flip-flop FF5 (as well as FF7) so as to reset, if necessary, the flip-flop back to its normal output port 02. In this manner, the information derived from the previous operating cycle with respect to a given staked resistor-frame assembly, which information would be stored in and represented by the particular operating state of the flip-flop FF5, is erased in preparation for the storage of new information during the then existing operating cycle.

Considering now the function of the time-out sensor S4 more specifically, each time a signal (zero magnitude) therefrom is applied through a channel 558 to the input control port C_1 of the gate 0/N11, an output signal would be supplied from the port 02 of that gate through a channel 605 and a channel 601 to the input control port C_3 of the gate 0/N12. This, in turn, would produce an output signal at the port 02, and would be transmitted through a channel 593 to the input control port C_2 of the flip-flop FF3, thereby removing fluidic pressure supplied from the output port 01 thereof to the staking valve SV1 and associated cylinder SC1. As a result, the pivotal lever 359 (FIG. 15) would raise the staking head 351 supported thereon upwardly, away from the staked resistor-frame assembly.

It should be understood that the resultant sensor S4 initiated switching of the operating state of the flip-flop FF3 would occur even though the Schmitt trigger ST6 may not have switched operating state to the output port 02 thereof in response to a mid-level magnitude of back pressure having been sensed. The resultant signal from the output port 02 of the flip-flop FF3 would thus be directed through the channel 595 to the input control port C_3 of the gate 0/N13.

From this gate, a signal would be transmitted from the output port 01 thereof through channel 587 to the input control port C_1 of the gate 0/N14. An input signal at the port C_1 (or C_3) of that gate would result in an output signal being exhausted to atmosphere through the output port 01 of the gate 0/N14. With no output signal thus appearing at the output port 02 of the latter gate, there would be no signal directed through the

channel 589 to the input control port C_3 of the flip-flop FF5.

No signal would likewise be applied to the input control port C_1 of the flip-flop FF5 for the operating condition where only the low-limit Schmitt trigger ST5 had switched operating state before the generation of a time-out signal by the sensor S4. This follows from the fact that upon the application of a zero time-out signal at the input control port C_1 of the gate 0/N11 from the sensor S4, an output signal would also have been supplied by the latter gate through channel 605 to the input control port C_2 of the flip-flop FF4. As a result, that flip-flop would switch operating state from the previous 01 to the 02 output state. It will be remembered that a sensor S3 initiated "Reject" signal previously applied to the input control port C_1 of the flip-flop FF4 would have produced an output signal at the port 01 thereof. With a signal thus removed from the output port 01 of the flip-flop FF4 at time out, in response to the operation of sensor S4, no input signal would be applied to the input control port C_3 of the one-shot multivibrator ST9.

The latter device would, therefore, continue to supply a signal out of the output port 02 thereof, through channels 612 and 613 to the input control port C_1 of the gate 0/N16. As such, there would be no output signal supplied from the output port 02 of the latter gate, through channel 617, to the input control port C_1 of the flip-flop FF5.

Accordingly, with no input signal being applied to either the C_1 or C_3 input control ports of the flip-flop FF5, that device would remain in its previously reset operating state from the time the sensor S4 initiated a time-out signal (see FIG. 20) during one operating cycle through at least the end of the "Eliminate Reject Memory" period in the subsequent operating cycle. As such, the continuous flip-flop produced input signal at the port C_3 of the gate 0/N15 would override or render ineffective the zero input signal applied to the input control port C_1 of that gate during the "Reject" period of the subsequent operating cycle. This ineffectual "Reject" signal would, of course, be received after a given staked-resistor-frame assembly found acceptable at the staking station 360 had been indexed to the staked resistor-reject station 380.

SECOND CIRCUIT CONDITION — ACCEPTABLE

In the second situation where the Schmitt trigger ST6 would also switch operating state, but some time after ST5, an output signal would be produced at the port 02 of the former and be directed through a channel 591 to the input control port C_1 of a gate 0/N12. This would result in an output signal being produced at the output port 02 of the gate 0/N12 and directed through a channel 593 to the input control port of the flip-flop FF3. This input signal would result in the flip-flop switching operating state from the 01 to the 02 output port thereof, thus removing a signal from the staking valve SV1.

As pointed out hereinabove, a signal is initially applied to the staking valve SV1 by the application of a momentary pressure signal from the sensor S3 to the input control port C_1 of the gate 0/N10. This occurs once each operating cycle during the simultaneous time periods indicated by the legends "Reject" and "Stake Down" in the timing chart of FIG. 20.

The removal of fluidic pressure from the staking valve SV1 would, of course, result in the staking cylinder SC1 associated therewith to retract, thereby raising the staking head 351 indirectly connected thereto away from a given staked resistor-frame assembly previously indexed into alignment therewith (see FIG. 15). An output signal from the port 02 of the flip-flop FF3, in response to the switching of the Schmitt trigger ST6, would also result in a signal being directed through the channel 595 to the input control port C₃ of the gate 0/N13. The latter gate would then produce an output signal at the port 01 thereof which would be transmitted through the channel 587 to the input control port C₁ of the gate 0/N14. This would result in no signal being produced at the output port 02 of the latter gate and, hence, no input signal being applied at the input control port C₃ of the flip-flop FF5. No signal would likewise normally be applied to the input control port C₁ of the flip-flop FF5 during a normal staking period. 20

With no input signal appearing at either the C₁ or C₃ input control ports of the flip-flop FF5 in the case of a staked resistor-frame assembly having switched both triggers ST5 and ST6, the flip-flop would remain in its previous reset state. As such, an output signal would continue to be directed through the channel 615 to the input control port C₃ of the gate 0/N15, not only at the completion of a staking operation, but until after receipt of the next "Eliminate Reject Memory" or reset signal which would be applied to the input control port C₂ of the flip-flop during the subsequent operating cycle. As will be remembered, this reset signal is supplied from the sensor S2 through the channel 547 for a short period of time during each operating cycle, as best seen in the timing chart of FIG. 20.

It is thus seen that upon the indexing of a staked resistor-frame assembly which attained a mid-point value of resistance to the staked-resistor accept-reject station 380, receipt of the subsequent momentary "Reject" signal at the input control port C₁ of the gate 0/N15, effected by sensor S3 and the gate 0/N10, would again have no effect in actuating the reject valve RV3. The particular frame assembly which resulted in the normal switching of both Schmitt triggers ST5 and ST6 during the staking period, would therefore not be ejected from the associated nest of the conveyor at the station 380.

Reference was made above to the fact that an input signal would normally not be applied to either of the control ports C₁ or C₃ of the flip-flop FF5 during a typical operating cycle. This is true if the staked resistor-frame assembly was found acceptable by the fluidic circuit. However, if a defective assembly was detected, an input signal would be supplied from either the gate 0/N14 or the gate 0/N16 to the input control ports C₃ or C₁, respectively, of the flip-flop FF5. Which input port would receive a signal, and when during the operating cycle, would depend on the nature of the sensed defective staked resistor frame assembly. The operating conditions indicative of these unacceptable situations will be discussed in greater detail hereinbelow.

It should be remembered that in the discussion of the fluidic staking and accept-reject circuitry hereinabove, reference has been made to the circuitry associated with only one of the two staking heads 351, there being

5 duplicate circuitry, including low limit and mid-limit Schmitt triggers ST7 and ST8, flip-flops FF6 and FF7 and OR/NOR gates 17-21 associated with the other staking head. More specifically, the two fluidic circuits associated with the two staking heads are directly equatable in terms of function and mode of operation as follows: ST5 to ST7, ST6 to ST8, FF3 to FF6, 0/N12 to 0/N19, 0/N13 to 0/N20, 0/N14 to 0/N17, FF5 to FF7, and 0/N15 to 0/N21. As for the flip-flop FF4, variable one-shot multivibrator ST9, and OR/NOR gates 0/N10 and 11, they are all common to each of the two fluidic staking and associated accept-reject circuits. With reference back to the simplified fluidic control circuitry disclosed in FIG. 19, it is readily seen that the following devices therein are common with those depicted in FIG. 22B: 451 to 0/N10, 452 to 0/N11, 456 to FF3, 457 to 0/N12, 461 to 0/N13, 462 to 0/N14, 465 to FF5, and 463 to 0/N15.

TWO OPERATING CIRCUIT CONDITIONS INDICATIVE OF UNACCEPTABLE ASSEMBLIES

First Circuit Condition — Unacceptable

25 The first operating condition relates to a situation where the resistor-frame assembly while being staked within the allotted time period would not result in the lowlimit Schmitt trigger ST5, for example, switching from the 01 to the 02 output port thereof. This could happen for a number of reasons. For example, one or both of the seated acoustic resistors could be defective, or one or both of the resistors could be missing from a given frame. In fact, even a frame could possibly be missing from a nest in isolated instances due to a loading malfunction.

30 In any event, whenever the trigger ST5 does not switch operating state there would be no signal supplied through channel 589 to the input control port C₁ of the gate 0/N13. There likewise would be no signal applied to the input control port C₃ of the gate 0/N13 during the period between the simultaneous "stake down" and "reject" periods and the S4 initiated "Stake Time Out" period. This follows from the fact that a momentary S3 initiated signal applied to the input control port C₁ of the gate 0/N10 would, in turn, produce an output signal at the port 01 thereof, which signal would be directed through channel 581 to the input control port C₁ of the flip-flop FF3. Thus, there would be no input signal applied through channel 595 to the input control port C₃ of the gate 0/N13 until an S4 time-out signal was received by the gate 0/N11.

35 Upon receipt of an S4 signal, a signal from the output port 02 of the gate 0/N11 would be directed through channels 605 and 601 to the input control port C₃ of the gate 0/N12. A signal would then be produced at the output port C₂ thereof and directed through channel 593 to the input control port C₂ of the flip-flop FF3. This signal would thereby reset the latter device, remove a signal from the staking valve SV1 and again result in a signal being supplied through channel 595 to the input control port C₃ of the gate 0/N13.

40 45 Also upon receipt of the sensor S4 signal, the previous output signal produced at the output port 01 of gate 0/N11 would no longer be applied to the input control port C₃ of the gate 0/N14. As there is a built-in time lag in a signal being directed from the 02 output

port of the gate 0/N11 through channels 605, 601, gate 0/N12, flipFLOP FF3, channel 595, gate 0/N13 and channel 587 to the input control port C₁ of the gate 0/N14, the latter gate would also have a zero signal at the control port C₁ thereof for a short period of time upon receipt of the S4 time-out signal. This delay would result in a signal being produced at the output port 02 of the gate 0/N14, and directed through channel 589 to the input control port C₃ of the flip-flop FF5.

As a result, the latter device would produce an output signal at the port 01 thereof until reset by a signal received at the input control port C₂ thereof from the sensor S2 during the subsequent operating cycle. Until reset, however, the flip-flop FF5 would provide an output signal exhausted to atmosphere, and thus, would supply no signal to the input control port C₃ of the gate 0/N15. Accordingly, when the subsequent sensor S3 initiated "reject" signal is received (during the next operating cycle) at the input control port C₁ of the gate 0/N10, it is seen that there would be a momentary period in which no output signal would be produced at the output port 02 of the latter device and, hence, no signal directed through channels 597 and 598 to the input control port C₁ of the gate 0/N15.

With there being no momentary input signals appearing at either the C₁ or C₃ input control ports of the gate 0/N15 during the subsequent "reject" period, the previously staked resistor-frame assembly would be ejected from its nest in response to the actuation of the appropriate reject valve, such as RV3, for example, and its associated reject cylinder RC3, which is identical to RC1 illustrated in FIG. 14.

As previously described in connection with the accept-reject circuitry and apparatus associated with the sensing or pre-inspect station 270, air is supplied from the supply line junction 482 (FIG. 21) to the particular air line 321 associated with a given staked resistor accept reject apparatus to facilitate the removal of an elevated defective assembly into an aligned chute 323 for disposal.

Second Circuit Condition - Unacceptable

The second operating condition is indicative of a different type of defect in the staked resistor-frame assembly than that described above wherein the low limit Schmitt trigger ST5 never switched operating state during the allotted staking period. More specifically, the second condition arises in situations where one or more of the acoustic disc-type resistors are not properly seated within the pre-formed apertures of the associated frame, where the frame is misaligned relative to the staking head, or where one or more of the resistors exhibits an abnormally high value of acoustic resistance. In those cases, the back pressure established as soon as the staking punches make contact with some part of the resistor-frame assembly may cause not only the low limit Schmitt trigger ST5 but the mid-limit trigger ST6 to abruptly change switching state, sometimes almost simultaneously. Such sudden triggering of both triggers within a time period that could not possibly have resulted in the satisfactory staking of the resistors to the frame is sensed by the fluidic delay line timing circuitry described briefly hereinabove. This circuitry is capable of producing a signal at the input control port C₁ of the flip-flop FF5, indicative of an unacceptable assembly, notwithstanding the switching of

both triggers ST5 and ST6. As such, the flip-flop is conditioned to effect the actuation of the reject valve RV1 and the ejection of the defective resistor-frame assembly during the "Reject" period of the subsequent operating cycle.

Considering the delay line timing circuitry in greater detail, upon receipt of a "Reject" signal from the sensor S3 to the input control port C₁ of the gate 0/N10, a signal would be directed from the output port 01 thereof through channels 607 and 614 to the input control port C₁ of a flip-flop FF4. This input signal, even though momentary (see timing chart), would produce a continuous output signal at the port 01 of the latter flip-flop until such time that an input signal would be applied to the control port C₂ thereof. Such a signal would subsequently be supplied in response to a zero time-out signal initiated by the sensor S4. This latter zero signal when applied would switch the operating state of the gate 0/N11 from the 01 to the 02 output port thereof and, thus, direct a signal through channel 605 to the input control port C₂ of the flip-flop FF4.

Before that time in the operating cycle, however, the sensor S3 (gate 0/N10, channel 607) initiated signal produced at the output port 01 of the flip-flop FF4 would be supplied through a channel 609 to the input control port C₃ of the variable one-shot multivibrator ST9. As previously mentioned, this multivibrator has a feed-back loop comprising a time-delay volume chamber V and an adjustable needle valve NV13 connected in series between the control ports C₁ and C₂ thereof.

The volume chamber is dimensioned and the needle valve adjusted such that upon the application of an input signal of a predetermined magnitude at the control port C₃ thereof for a predetermined period of time, a back pressure will be established at the control port C₂ of sufficient magnitude so as to switch the operating state of the multivibrator ST9 from the initial 01 output port back to the 02 output port, notwithstanding the continued presence of an input signal at the control port C₃ thereof. The time required to switch back to the 02 port is chosen to encompass that portion of the operating cycle starting with the "stake down" period and ending with the "Eliminate Reject Memory" period (see timing chart, FIG. 20). The significance of this time delay is perhaps best seen by the following illustration.

Assume that the Schmitt triggers ST5 and ST6 changed operating state so quickly during the staking period that the variable one-shot multivibrator ST9, in response initially to a sensor S3 (gate 0/N10, channel 607) initiated signal from the flip-flop FF4, could not establish sufficient back pressure at the control port C₂ thereof to switch back from the 01 to the 02 output port thereof. In that event, no signal would be directed through channel 612 to the input control port C₁ of the gate 0/N16. With no input signal likewise being applied to the input control port C₃ of the gate 0/N16, by reason of the gate 0/N12 switching operating state in response to the operation of the Schmitt trigger ST6, an output signal would be produced at the port 02 of the gate 0/N16 and directed through channel 617 to the input control port C₁ of the flip-flop FF5. This would result in no output signal at the port 02 of the flip-flop FF5 and, thus, no signal at the input control port C₃ of the gate 0/N15.

Accordingly, when the "Reject" period would occur during the next operating cycle, there would likewise be no output signal directed from the output port 02 of the gate O/N10 through channels 597 and 598 to the input control port C₁ of the gate 0/N15. Thus, with no signal being applied to either the C₁ or C₃ input control ports of the gate 0/N15, a signal would be applied to the reject valve RV3. As previously mentioned, this valve would, in turn, actuate the associated reject cylinder RC3 (identical to RC1 shown in detail in FIG. 14, and both shown symbolically in FIG. 21) so as to facilitate the removal of the previously detected defective staked resistor-frame assembly. This operation is accomplished, as previously mentioned, in conjunction with a continuous air blast being directed against the defective assembly through an air line 321 supplied with air from the supply junction 482 in FIG. 21. It should be remembered that there are actually four air lines 321 embodiment in the illustrative embodiment as shown in FIG. 1B, each one being associated with a different nest position and reject cylinder. These air lines, of course, could be controllably supplied with air by being directly and respectively coupled to the output ports of the reject valves RC1-RC4 associated with the reject cylinders illustrated in FIG. 21.

From the foregoing, it can be seen that once the flip-flop FF4, one-shot multivibrator ST9 and gate 16 in combination, have applied a signal to the input control port C₁ and switched the operating state of the flip-flop FF5 to the output port 01 thereof, indicative of an unacceptable staked resistor-frame assembly, the subsequent application of a sensor S4 time-out signal at the input control port C₂ of the flip-flop FF4 would be of no consequence with regard to conditioning the flip-flop FF5 so as to effect the actuation of the reject valve RV3 during the subsequent operating cycle. It should be understood that the flip-flop FF4 and the one-shot multivibrator, as well as the gate 0/N16 associated with the latter, in combination, comprise defective-assembly timing circuitry common to the two identical fluidic staking circuits respectively associated with the two staking heads 351 (shown in detail in FIG. 15 and symbolically in FIG. 21).

By way of general interest, the stake cycle timeout circuitry, including sensor S4, was found to be necessary for several reasons. First, in actual practice it was ascertained that an appreciable number of staked acoustic resistor-frame assemblies were not reaching the desired midpoint value of resistance so as to switch the mid-limit Schmitt trigger ST6 within the allotted staking time of the apparatus and, as a result, these staked assemblies were being ultimately rejected by the fluidic circuit even though they were actually acceptable from a use standpoint.

It was never conclusively determined why the mid-point couldn't consistently be reached, but it appeared to be related to excessive variations in resistance exhibited by the acoustic resistors as purchased, as well as to variations in the amount of metal moved during the staking operation. A further possibility is that the staking cylinder did not have enough driving power in the illustrative embodiment. Regardless of the reason(s), it was decided that the fluidic circuit should incorporate logic circuitry of the type described hereinabove to insure that those staked resistor-frame assemblies that were found through fluidic measurement to exhibit

values of acoustic resistance above a predetermined low limit but below a midpoint limit, should nevertheless be found acceptable.

As for the stake cycle time, it has been found that it can be reduced to an interval as short as about 300 milliseconds without a serious degradation in the accuracy of the dynamic acoustic resistance adjustment. Cycle times shorter than 300 milliseconds, however, have been found less reliable as a result of a deterioration in the response time of the driving power cylinders for the staking punches.

SUMMARY

In summary, the new method and apparatus embodied and claimed herein has made possible very sensitive and reliable fluidically controlled sensing, pre-inspecting, dynamic resistance adjusting and accepting-rejecting of disc-type acoustic resistors. Advantageously, the simultaneous staking and dynamic resistance adjusting is accomplished within a stake cycle time of approximately 500 milliseconds.

The composite fluidic circuit embodied herein also has provided a no-moving part, non-electrical, low hysteresis solution of the analog-to-digital conversion and amplification of very low differential pressure signals of the order of approximately 500 milliinches of water. Moreover, there advantageously are no manual inputs to the fluidic circuit embodied in FIGS. 21 and 22.

Another advantage of the fluidic control circuit is that it advantageously enables the stake cycle time to be readily varied over an appreciable time range. This is helpful in initially determining the nominal acoustic resistance value which will yield the optimum overall acoustic performance and stability for not only new receiver or transmitter units, but also whenever there is a design change made in any part of such of unit.

WHAT IS CLAIMED IS:

1. Apparatus for assembling a first part having at least one second part-receiving aperture therein with a second part exhibiting a compressive force-dependent density and a density-dependent resistance to the transmission of a flowable medium therethrough, comprising:

first means for forcibly securing by material flow at least one second part within an associated aperture of said first part;

second means for producing and directing at least a portion of a flowable medium through said second part, and

third means responsive to the magnitude of said flowable medium for controlling the force exerted upon said first and second parts by said first means so that the density-dependent resistance exhibited by said second part to the transmission of said flowable medium therethrough may be controlled within a predetermined range.

2. Apparatus in accordance with claim 1 wherein said third means includes a fluidic circuit responsive to the back pressure established by the resistance exhibited by said second part to the transmission of said flowable medium therethrough during the securement thereof within the aperture of said first part, said fluidic circuit further including means for generating a signal indicative of an unacceptable securement of a first

part-second part assembly whenever the measured magnitude of back pressure does not fall within said predetermined range.

3. Apparatus in accordance with claim 2 wherein said first securing means comprises a pressure source and a piston driven pneumatically controlled cylinder, said piston supporting and driving securing punches corresponding in number with the second part receiving apertures formed in said first part, and wherein the actuating pressure supplied to said pneumatic cylinder is under the variably timed control of said fluidic circuit.

4. Apparatus for assembling first and second piece parts wherein said second piece part is of a porous nature allowing at least partial transmission of a flowable medium therethrough, comprising:

an indexible nest carrying conveyor for transporting a succession of piece part receiving nests secured therealong to a succession of work stations;

a first loading station including means for positioning first parts each having at least one second piece part receiving aperture therein in respective nests advanced by said conveyor to a position in alignment therewith;

a second loading station including means for successively feeding a number of said second parts corresponding in number to the receiving apertures in said first part to and in seating relationship with said apertures;

a pre-inspect station including means for sensing for the presence of and whether each of said second parts has been properly seated within a given aperture of said first part, and for generating a control signal in the event that a first part of said associated second parts have not been initially properly positioned relative to each other;

a staking station including force controllable staking means for permanently securing properly positioned second parts within the respective receiving apertures of said first part, and for generating a control signal in the event that said first and second parts have not been satisfactorily staked, and

means responsive to a control signal from either said pre-inspect station or said staking station for ejecting from a given nest of said conveyor any first part-second part assembly which resulted in the generation of a control signal.

5. Apparatus in accordance with claim 4 wherein said means at said pre-inspect station for sensing for the presence and proper seating of said second parts relative to an associated first part comprises a fluidic circuit directing a controllable flowable medium to said first part and confined to only those areas where said second parts should normally be seated, and said circuit further including fluidic means for measuring the magnitude of the back pressure established because of the partial resistance exhibited by said second parts to the transmission of said flowable medium therethrough, and for differentiating between satisfactory and unsatisfactory magnitudes of back pressure, and for generating a control signal indicative of first and second piece parts which are not properly assembled loosely in the desired relationship.

6. Apparatus in accordance with claim 5 wherein said force controllable staking means at said staking station comprises a pressure source and a pneumatically controlled, piston driven staking cylinder, said piston supporting and driving a number of staking punches corresponding in number with the second part-receiving apertures formed in said first part, and further including means for simultaneously establishing and directing a predetermined flowable medium partially through each of said second parts seated within associated apertures of said first part, and for measuring the magnitude of the back pressure established because of the partial resistance exhibited by said second parts to the transmission of said flowable medium therethrough, the magnitude of said back pressure being utilized as a control parameter to control the pressure applied to said pneumatic cylinder and, thereby, to control the degree of permanent compressive force exerted by said piston driven punches on said first part-second part assembly during the staking operation, and said staking means further including circuit means for generating a control signal in response to a signal from said means for measuring the back pressure whenever a given first part-second part assembly cannot be permanently assembled by the staking operation so as to produce a measured back pressure falling within a predetermined range.

7. Apparatus in accordance with claim 4 further comprising:

an orienting station comprising means for angularly moving each successively loaded first part to a desired position relative to and on an associated nest prior to said second piece parts being seated within respectively aligned apertures of said first part.

8. Apparatus for positioning and staking acoustic resistors exhibiting a compressive force-dependent density and a density-dependent resistance to the transmission of a flowable medium therethrough in pre-formed apertures of a frame member of an electrical transducer comprising:

a nest carrying conveyor for feeding a succession of frame receiving nests secured therealong to a succession of work stations;

a frame loading station including means for positioning successive frame members of an electrical transducer into successively advanced and aligned nests during each successive indexing of said conveyor;

an acoustic resistor loading station including means for successively feeding a different acoustic resistor into each of said pre-formed apertures of a frame positioned in alignment therewith during each advancement of said conveyor;

a resistor staking station including means for staking each acoustic resistor positioned within an associated aperture to said frame, and further including means for simultaneously creating a controllable flow of a predetermined medium through each acoustic resistor seated within a given aperture of said frame, and for monitoring the back pressure established by, and the magnitude of which is dependent on, the resistance exhibited by all of said resistors to the flow of said medium therethrough, the magnitude of said back pressure

being utilized as a control parameter to control the degree of force exerted by said staking means against each aligned frame-resistor assembly so as to vary the density of and thereby dynamically adjust the value of acoustic resistance of the staked resistors within a predetermined acceptable range, said resistor staking station further including means for generating a reject control signal in response to a signal from said means for monitoring the back pressure whenever the acoustic resistors cannot be adjusted to a desired value during the staking operation, and

a staked-resistor reject-accept station including means responsive to said reject control signal from said acoustic resistor staking station for actuating ejection means to remove a given defective staked resistor-frame assembly from a given nest when indexed to the staked resistor reject-accept station.

9. Apparatus in accordance with claim 8 wherein said means at said staking station for creating a controllable flow of a predetermined medium and for monitoring the back pressure produced by the presence of the acoustic resistors positioned within an associated frame comprises a fluidic circuit, with said medium comprising air.

10. Apparatus in accordance with claim 9 further comprising:

a frame orienting station including means for angularly moving each of said frames to a desired position relative to and on an associated nest so as to consistently insure that said pre-formed apertures

in said frame are in alignment with apparatus associated therewith at each successive work station when advanced thereto.

11. Apparatus in accordance with claim 8 further comprising:

a loaded acoustic resistor sensing station including means for sensing whether all of said acoustic resistors associated with a given frame have been fed to and properly seated within the respective pre-formed apertures of said frame, said sensing means including means for establishing a controllable flow of said predetermined medium through each of said seated acoustic resistors, and for monitoring the resultant back pressure established by the number of said resistors present, said last-mentioned means being capable of differentiating between a condition wherein all of said resistors are present and properly seated within the respective apertures in said frame from a condition wherein said resistors are not all present and properly seated, and for generating a second reject control signal whenever the latter condition exists, and wherein said apparatus further includes a loaded-resistor reject-accept station including means responsive to said second reject control signal from said sensing station for actuating ejection means to remove a given defective sensed loaded resistor-frame assembly from a given nest when indexed to the loaded resistor reject-accept station.
